ABSTRACT

To control at least one solenoid operated fuel injection valve in dependence upon the rate of air flow, and particularly to avoid interference with stray signals generated in the electrical system associated with an internal combustion engine, an air flow meter is arranged in the induction pipe of the engine which has an output providing signals in digital form, for example by controlling the frequency of an oscillator which is then converted into digital signals by a frequency/digital converter. The digital signals are applied to a computing circuit which includes a digital differential analyzer and an interpolator, or function generator which is connected therein and so set that it simulates the operating characteristics of the internal combustion engine to modify the digital signal and provide an output which can be converted by a frequency/time converter to a timing signal to control the solenoid of the fuel injection valve and open the fuel injection valve for a predetermined period of time, depending on rate of air flow, or other engine parameters, and as adjusted for the operating characteristics of the engine over its operating range.

CONTROL SYSTEM AND DEVICES FOR INTERNAL COMBUSTION ENGINES

The invention relates to a control device for a fuel injection system of an internal combustion engine, having a computing circuit.

In a fuel injection system as described in U.S. Ser. 798,650, a computing circuit is provided for controlling at least one injection valve in dependence upon the rate of air flow as measured by an air flow meter arranged in the engine induction pipe. Direct voltage signals are formed in the computing circuit and are proportional to the rate of air flow and the rotational speed of the crankshaft. These signals are further processed as analog signals in direct voltage amplifier stages. Such direct voltage amplifier stages serving as analog computers have to be adjusted very accurately and cause considerable difficulties with respect to their long-term stability. Furthermore, analog computing circuits are very sensitive to interference pulses which are produced in motor vehicles by, for example, the ignition system or the direction indicators.

It is an object of the invention to provide a control device for an internal combustion engine, for controlling at least one solenoid operated fuel injection valve in dependence upon the rate of air flow, which is reliable and essentially immune to disturbing influence.

SUBJECT MATTER OF THE INVENTION:

An air flow meter is arranged in the induction pipe of the engine and provides digital air flow output signals. A computing circuit has an input connected to receive the digital output signals. The computing circuit output controls the solenoid of the fuel injection valve. The computing circuit comprises a digital differential analyzer and at least one interpolator serving as a store for simulating the operating characteristics of the internal combustion engine.

In accordance with a feature of the invention, and particularly for use in automotive vehicles, the air flow meter comprises an air flow sensitive element which controls the frequency of an oscillator such that its output frequency is dependent upon the rate of air flow. A frequency/digital converter then provides the digital output. The frequency/digital converter then preferably is the input circuit for the digital differential analyzer.

A frequency/digital converter converts an input frequency (whose value may be an analog of an operating parameter of the engine, such as the rate of air flow) into a digital output. An interpolator processes a digital input (in this case the output of the frequency/digital converter) in accordance with predetermined functions to produce a digital output dependent upon the interpolator input in accordance with said functions (which may represent one or more known operating characteristics of the engine). The frequency/digital converter and the interpolator contain counters which require no adjustment. Interference pulses may possibly cause slight errors in counting but such errors can be made negligible if sufficiently high frequencies are chosen.

The digital differential analyzer is in the particular description with reference to the drawings referred to as an "incremental computing circuit" since, in the same manner as in an analog computer, the function value is stored in a counter once it has been calculated,

and only the variation or the increment of the function is added to the stored function value in a subsequent interval of time. Therefore, the digital differential analyzer operates to a large extent like an analog computer and, nevertheless, can achieve the same accuracy as a conventional digital computing circuit, since the calculated function value is present in the counter in the form of a binary number having a plurality of digits. The accuracy can be increased by increasing the number of digits of the binary numbers. Of course, the number of digits is limited by the required rate of computing.

The functions or characteristics, according to which the injected quantity of fuel have to depend upon operating parameters, such as the engine speed or the rate of air flow in order to obtain optimum combustion of the air/fuel mixture, can be ascertained experimentally in an internal combustion engine. These functions are to be simulated by the computing circuit and, for this reason, have to be stored therein. In the digital differential analyzer, the interpolator serves as a store for the functional interrelationships designated "fields of characteristics," and converts an input frequency into an output frequency which is generally non-linearly dependent upon the input frequency. Thus, the functions or fields of characteristics ascertained experimentally can be adapted to any desired internal combustion engine.

There are two different types of fuel injection systems. In one type, the injection valves are operated intermittently and are opened for a specific injection period at each stroke of the associated cylinder of the internal combustion engine. The quantity of fuel injected is at least approximately proportional to the injection period, since the valves are fully opened during this period. In the other type, the injection valves are open continuously. The flow cross section, and thus the quantity of fuel injected into the induction pipe per unit of time, is proportional to a control current which is fed to the solenoids of the injection valves.

The control device in accordance with the invention can be adapted to the first type of fuel injection system in which intermittently operating injection valves are provided for metering the fuel, by feeding the output frequency of at least one interpolator to a frequency/time converter for the purpose of controlling the injection valves. The frequency/time converter serves to convert the output frequency of the interpolator into an injection period proportional thereto.

The control device of the present invention can be adapted to the second type of fuel injection system in which continuously operating injection valves are provided for metering the fuel, by feeding the output frequency of at least one interpolator at least indirectly to the electrical inputs of the injection valves. If it is ensured that the output frequency of the interpolator consists of pulses of constant length, the average current strength fed to the injection valves is proportional to this output frequency of the interpolator. The inductance of the solenoid serving to open an injection valve serves to form the average value of the current.

When the digital differential analyzer is used to control the fuel injection system, it is preferable for it to also effect the so-called warming-up enrichment of the fuel/air mixture, since an internal combustion engine requires a richer mixture when in the cold state. The mixture can be enriched during the warming-up phase

if the electrical output of a temperature sensor in thermal contact with the engine block of the internal combustion engine is connected to the input of a voltage/frequency converter, the output of the oscillator is connected to a first frequency/digital converter, and the output of the voltage/frequency converter is connected to a second frequency/digital converter.

A plurality of non-linear fields of characteristics of the internal combustion engine can be superimposed by connecting a respective interpolator to the output of each frequency/digital converter.

The air flow meter fitted in the induction pipe measures a quantity of air which flows through the induction pipe per unit of time. A specific quantity of fuel is likewise injected into the induction pipe per unit of time in the case of continuously operating injection valves. Therefore, a further correction circuit is not required and the output frequencies of the interpolators can be fed without further processing to the solenoids of the injection valves. On the other hand, in the first type of fuel injection system which includes intermittently operating injection valves, a further correction circuit is required to take into account the speed of the internal combustion engine.

The open periods of the inlet valves are shorter at higher speeds of the internal combustion engine, so that the internal combustion engine draws in a smaller quantity of air per stroke with the same measured rate of air flow per unit of time. Thus, the speed of the internal combustion engine also has to be taken into account for accurately calculating the quantity of fuel to be injected. This can be achieved if the second interpolator and the pulse tachogenerator are connected to two inputs of a divider, the outputs of the first interpolator and the divider are connected to two inputs of a multiplier, and the output of the multiplier is connected to the input of the frequency/time converter whose output serves for controlling the injection valves.

The frequency/time converter converts the output frequency of the computing circuit into an injection period proportional thereto.

The above-described features of the control device in accordance with the invention at the same time enable the exhaust gases to be relatively uncontaminated with obnoxious substances, since the above-mentioned simulation of the fields of characteristics of the internal combustion engine leads to optimum combustion of the air/fuel mixture. The cleanliness of the exhaust gases can be still further improved however if an oxygen measuring sensor is arranged in an exhaust gas collecting manifold of the internal combustion engine, the output of the oxygen measuring sensor being connected to a further input of the computing circuit by way of a voltage/frequency converter. The oxygen measuring sensor ascertains the accuracy with which the optimum fuel/air mixture has been calculated.

The injection period calculated by the computing circuit in dependence upon the operating parameters of the internal combustion engine can be corrected in a particularly accurate manner in dependence upon the output signal of the oxygen measuring sensor if a servo-loop having a subtractor for comparing the desired value with the actual value is provided for the air number of the air/fuel mixture fed to the internal combustion engine, and if the voltage/frequency converter is connected to a first input of the subtractor and a desired value setter is connected to the second input of

the subtractor. (The air number λ represents the mass ratio of air to fuel and is chosen to be 1.0 for a stoichiometric mixture).

By virtue of the described circuit arrangement, the computing circuit becomes a component part of the servo-loop which controls the injection period in dependence upon the actual measured composition of the air/fuel mixture.

The construction of the control device, as a servo-loop has a further advantage that the computing accuracy does not have to be so high. That is to say, a small error in the calculated injection period is immediately corrected by the servo-loop. Therefore, in the embodiment having a servo-loop, the total expenditure on circuitry is only slightly greater than in the embodiment without such a feedback loop.

The invention is further described hereinafter, by way of example, with reference to the accompanying drawings, in which:

FIG. 1 is a schematic diagram of an internal combustion engine having various measuring transducers;

FIG. 14b is a pulse diagram for explaining the mode of operation of the divider illustrated in FIG. 14a;

FIG. 15 is a circuit diagram of a decoder for the angle of the butterfly valve of the engine of FIG. 1;

FIG. 16a is a circuit diagram of a voltage/frequency converter of FIG. 1; and

FIG. 16b is a pulse diagram for explaining the mode of operation of the voltage/frequency converter illustrated in FIG. 16a.

Referring to FIG. 1, an internal combustion engine 20 of a mechanically propelled vehicle draws in combustion air by way of an air filter 21 and an induction pipe 22. A butterfly valve 23 is arranged in the induction pipe 22 and is operable by means of an accelerator pedal 24. This is indicated by a broken line 45.

A baffle plate 25 is movably mounted in a widened portion 24a provided in the induction pipe 22 between the air filter 21 and the butterfly valve 23. An iron core 26 is mechanically connected to the baffle plate 25. The iron core 26 enters a coil 27 which is a component part of a resonant circuit (not illustrated). The resonant circuit forms a part of a LC oscillator 28. The parts 25 to 28 constitute an air flow meter.

Fuel can be injected into the branches of the induction pipe 22 directly upstream of the engine inlet valves (not illustrated) by means of injection valves 29, 30. For reasons of clarity, only two of the four injection valves 29, 30 for a four-cylinder internal combustion engine are illustrated in FIG. 1. The other two cylinders also have associated injection valves. The injection valves 29, 30 are supplied with fuel from a fuel line 31 and are operated electro-magnetically by solenoids 32, 33. The two solenoids 32, 33 are connected to a terminal 34 which is connected to the output of a computing circuit (FIG. 3a).

The exhaust valves (not illustrated) of the internal combustion engine 20 are connected to individual exhaust gas branches of an exhaust gas collecting manifold 35. The exhaust gas collecting manifold 35 accommodates an oxygen measuring sensor 36 whose construction will be described below with reference to FIG. 2a. The electrical output of the oxygen measuring sensor 36 is connected to a voltage/frequency converter 37. The voltage/frequency converter 37 comprises a voltage-controlled oscillator which will be described more fully hereinafter with reference to FIG. 16a.

A temperature sensor 38 is in thermal contact with the engine block of the internal combustion engine 20. The input of a voltage/frequency converter 39 (of the same construction as the voltage/frequency converter 37) is connected to the electrical output of the temperature sensor 38.

The crankshaft 40 of the internal combustion engine 20 drives a pulse tachogenerator 41. The tachogenerator 41 includes a toothed wheel 42 which rotates in synchronism with the speed of the crankshaft. The toothed wheel 42 has ferro-magnetic teeth which pass between the limbs of a ferro-magnetic yoke 43 when the toothed wheel turns. A coil 44 is wound on the yoke 43.

As is indicated by the broken line 45, the butterfly valve 23 actuates two switches 46, 47, the first of which switches is closed during idling and the second is closed when the butterfly valve is fully open. The outputs of the two switches 46, 47 are connected to inputs of a decoder 48 whose output is designated g_5 . The decoder 48 is hereinafter described with reference to FIG. 15.

When the internal combustion engine is operating, the baffle plate 25 of the air flow meter, is moved away from its left hand stop (not shown) to an extent which increases with the rate of air flow, i.e. with the air mass inducted per unit of time. Therefore, the inductance of the coil 27 is reduced as the rate of air flow increases, and the output frequency f_1 of the LC oscillator 28 becomes greater. Non-linearities of the frequency response can be compensated for by suitably shaping the iron core 26.

When the internal combustion engine 20 is operating, the output of the decoder 48 produces a binary number g_5 whose numerical value is dependent upon the position of the butterfly valve.

15 The output of the pulse tachogenerator 41 produces alternating voltage pulses whose frequency is designated f_3 . The magnetic reluctance of the magnetic flux path formed by the yoke 43 and the toothed wheel 42 varies periodically during rotation of the toothed wheel 20 42. Thus, there are induced in the coil 44 alternating voltage pulses whose frequency is proportional to the rotational speed of the crankshaft 40.

During operation of the internal combustion engine, the outputs of the two voltage/frequency converters 37, 39 deliver frequencies designated f_6 and f_2 respectively.

25 The construction of the oxygen measuring sensor 36 is illustrated diagrammatically in FIG. 2a. The measuring sensor comprises a short tube 49 which is closed at one end and which is sintered from a solid electrolyte.

30 Microporous platinum layers 50 are applied to both sides of the solid electrolyte 49 by vapour deposition. The two platinum layers 50 are provided with contacts which are connected to electrical connection terminals 51, 52. The solid electrolyte tube 49 is held in the wall 35 of the exhaust gas collecting manifold 35 by means of a holder 53. The holder 53 has a bore 54 through which atmospheric air can enter the interior of the tube 49. Exhaust gas flows around the outer surface of the tube 49.

40 The solid electrolyte conducts oxygen ions at high temperatures such as prevail in the flow of exhaust gas. By way of example, zirconium dioxide can be used as the solid electrolyte. When the partial pressure of the oxygen in the exhaust gas differs from the partial pressure of the oxygen in the atmospheric air, a potential difference U occurs between the two connection terminals 51, 52. The characteristic of this potential difference, plotted against the air number λ , is shown by a curve 55 in FIG. 2b. This potential difference is logarithmically dependent upon the quotients of the partial pressures of the oxygen on each side of the solid electrolyte 49. Therefore, the output voltage of the oxygen measuring sensor varies abruptly in the vicinity of the air number $\lambda = 1.0$.

45 As the air number λ representing the mass ratio of air to fuel fed to the engine, is defined to have the value 1.0 when the air/fuel mixture is stoichiometric, it is less than 1.0 for a rich mixture and greater than 1.0 for a lean mixture.

55 FIG. 3a shows the first embodiment of a digital differential analyzer or "digital incremental computing circuit" as it is called hereinafter which serves to control intermittently operating injection valves. The output terminal 34 of this computing circuit is the terminal 34 which is shown in FIG. 1 and which serves to control the injection valves 30, 29. The output frequency f_1 of the LC oscillator 28 (which is an analog of the air quantity) is fed to a first input terminal 56. A series combi-

60

65

nation comprising a first frequency/digital converter 57 and a first interpolator 58 is connected to the first input terminal 56. The output frequency f_2 of the voltage/frequency converter 39 (which is an analog of the engine temperature) is fed to a second input terminal 59. A series combination comprising a second frequency/digital converter 60 and a second interpolator 61 is connected to the second input terminal 59 of the computing circuit illustrated in FIG. 3a. At the outputs of the two interpolators 58, 61 appear pulse trains whose average frequencies are designated f_{11} and f_{21} respectively. As will later become apparent, the frequencies f_{11} and f_{21} comprise digital information relating to the air quantity and the engine speed. A third input terminal 62 of the computing circuit illustrated in FIG. 3a and the output of the second interpolator 61 are connected to two inputs of a divider 63. The output frequency f_3 of the pulse tachogenerator 41 (which is an analog of the engine speed) is fed to the third input terminal 62. The frequency f_{21} is fed to the divider 63 as the dividend, and the frequency f_3 is fed thereto as the divisor. The outputs of the first interpolator 58 and the divider 63 are connected to two multiplying inputs of a first multiplier 64 whose output is connected to a second multiplier 65. The output g_5 of the decoder 48 (which comprises binary information relating to the butterfly valve angle) is connected to the second multiplying input of the second multiplier 65.

The voltage of the vehicle power supply is taken into account as a further correction quantity in the computing circuit. For this purpose, a fourth input terminal 66 of the computing circuit shown in FIG. 3a is connected to the positive pole of the vehicle battery (not illustrated). The fourth input terminal 66 is connected to a voltage/frequency converter 67 which supplies an output frequency f_4 (which is an analog of the battery voltage). The output of the voltage/frequency converter 67 is connected to the input of a frequency converter 68 whose output frequency is designated f_{41} (which comprises digital information relating to the battery voltage).

An adder 69 is connected to the input of a frequency/time converter 70 whose output terminal 34 controls the injection valves 29, 30. The output of the frequency/time converter 70 supplies pulses whose duration T_1 is proportional to the input frequency. The outputs of the second multiplier 65 and the frequency converter 68 are connected to the two inputs of the adder 69.

In this specification, the term "frequency" is used in a general sense. In this general sense, the average pulse frequency per unit of time is designated "frequency." The pulses in the output pulse trains of the interpolators and multipliers comprising digital information do not follow one another periodically, but are generally distributed non-uniformly. Nevertheless, the term "frequency" can be used in connection with such pulse trains, since the average pulse frequency per unit of time remains constant with constant input signals. The digital information is represented by this average pulse frequency. An example of such a pulse frequency will be further described below with reference to FIG. 4b.

The output of the computing circuit illustrated in FIG. 3a comprises the pulses from the frequency/time converter 70 having the pulse duration T_1 and serves to control the intermittently operating fuel injection valves. The pulse duration T_1 is approximately propor-

tional to the quantity of fuel injected. The quantity of fuel injected has to be proportional to the quantity of air drawn in. Since the air flow meter 25-28 measures a quantity of air per unit of time by means of the baffle plate 25, the speed of the internal combustion engine must also be taken into account by the computing circuit. If the quantity of air drawn in per unit of time is maintained constant, an individual cylinder draws in a smaller quantity of air per stroke at higher engine speeds than at lower engine speeds, since the inlet valve is maintained open for a specific angle of rotation of the crankshaft. Therefore, when the quantity of air is maintained constant per unit of time, the duration T_1 of the injection pulse must become smaller as the speed of the internal combustion engine increases. The computing circuit has the task of ascertaining the quotient f_{11}/f_3 .

Furthermore, the temperature of the engine block has to be taken into account, since the internal combustion engine has to be operated with a richer air/fuel mixture during the warming-up phase. In the first embodiment illustrated in FIG. 3a, the frequency f_2 supplied by the temperature sensor 38 and the voltage/frequency converter 39 is combined multiplicatively with the frequency f_1 . Since the duration T_1 of the injection pulse should be reduced with increasing engine temperature, the input frequency f_2 must also be reduced with increasing temperature. This can be achieved in a simple manner if the temperature sensor 38 comprises an NTC resistor connected to the input of the voltage/frequency converter 39 which is of the kind illustrated in FIG. 16a yet to be described.

The relationship between the quantity of air drawn in and the quantity of fuel to be injected is generally non-linear. Therefore, the output frequency f_1 of the air flow meter 25-28 has to be converted in the first interpolator 58 into the frequency f_{11} which is non-linearly dependent upon the input frequency f_1 . The characteristic of the interpolator 58 has to be adapted as accurately as possible to the measured characteristic of the internal combustion engine 20 to which the computing circuit is fitted. Each internal combustion engine has its own characteristic by which the fuel/air mixture should become gradually leaner during the warming-up phase. The relationship between the temperature of the engine block and the quantity of fuel to be injected is generally non-linear. The second interpolator 61 serves to simulate this warming-up characteristic so that the frequency f_{21} is non-linearly dependent upon the input frequency f_2 .

The quotient of the frequencies f_{21} (non linearly dependent upon the engine temperature) and f_3 (proportional to engine speed) is formed in the divider 63. This quotient is multiplied in the first multiplier 64 by the output frequency f_{11} of the first interpolator 58 (non-linearly dependent upon the rate of air flow). The binary number g_5 which is dependent upon the position of the butterfly valve is fed to the second multiplier 65 as a further correction quantity. The reason for this correction quantity resides in the fact that the internal combustion engine can be operated with a relatively lean mixture (air number $\lambda = 1.0$) when the butterfly valve is between its idling and fully open positions. A richer mixture may be used during idling and full throttle operation of the internal combustion engine. Thus, a pulse train f_{65} of a frequency in which the rate of air flow, the temperature of the internal combustion en-

gine, the speed of the internal combustion engine and the position of the butterfly valve have already been taken into account appears at the output of the second multiplier 65. In principle, this output pulse train could be fed directly to the frequency/time converter 70. However, it has proved to be advisable also to take the electrical voltage of the vehicle power supply into account, since the injection valves are opened more slowly with a lower supply voltage. The voltage/frequency converter 67 is provided in order to take the voltage of the vehicle power supply into account, the output frequency of which converter is proportional to the voltage of the vehicle power supply.

Referring momentarily to FIG. 6, the frequency converter 68 is in the form of a simplified divider and its output produces the frequency f_{41} which increases as the voltage of the vehicle power supply decreases. Thus, the injection period T_1 becomes shorter with a higher voltage of the vehicle power supply.

The output frequency f_{41} of the frequency converter 68 is additively combined in the adder 69 with the output frequency f_{65} of the second multiplier 65 to produce a frequency f_7 which comprises digital information representing the desired injection period T_1 . Although a multiplicative combination of the two frequencies f_{41} and f_{65} would be more the ideal, multiplication is not necessary, since the maximum influence of the voltage of the vehicle power supply on the injection period T_1 is of the order of 10% so that the error arising through addition rather than multiplication of the two frequencies is negligible. Thus, five input quantities, namely the frequencies f_1 to f_4 and a binary number g_5 , are taken into account when calculating the injection period T_1 .

FIG. 3b shows the block circuit diagram of a second embodiment of digital incremental computing circuit which serves to control continuously operating fuel injection valves. The second embodiment essentially includes the same structural groups as the first embodiment. Only the divider 63 is omitted, so that the output of the second interpolator 61 is connected via a frequency/binary converter (not shown) to the input of the first multiplier 64. The frequency/time converter 70 is also omitted. Otherwise the circuit shown in FIG. 3b is identical to the circuit of the first embodiment shown in FIG. 3a. The same reference numerals have also been used.

The divider 63 can be omitted in the second embodiment since, on the one hand, the air flow meter 25-28 ascertains the quantity of air flowing through the induction pipe 22 per unit of time and, on the other hand, the continuously operating injection valves 29, 30 inject a specific quantity of fuel into the induction pipe per unit of time. Since the quantity of air and the quantity of fuel per unit of time are measured and metered respectively, speed correction can be omitted in the case of the continuously operating injection valve. The open duration of the inlet valves of the individual cylinders no longer need be taken into account. The frequency/binary converter (not illustrated) converts the output frequency f_{21} of the second interpolator 61 into a binary number for application to one of the inputs of the multiplier 64.

Such continuously operating injection valves are known. They are operated by solenoids 32, 33 (FIG. 1) which, in accordance with the strength of the magnetizing current open the flow cross section for the fuel to

a greater or lesser extent. The control current is fed to the solenoid 32, 33 in the form of pulses whose length is equal to, for example, the pulse length of the pulse train f_{05} (see FIG. 11b). By using pulses which have a constant duration, the average current strength in the solenoids 32, 33 is proportional to the pulse frequency f_7 at the output of the adder 69, the frequency f_7 comprising digital information in this embodiment representing the desired quantity of fuel per unit of time.

Furthermore, the average current strength in the solenoids 32, 33 also depends upon the voltage of the vehicle power supply, since this voltage influences the amplitude of the pulses. Therefore, an additive voltage correction having the frequency f_{41} is also provided in the second embodiment illustrated in FIG. 3b. Here, also, the frequency f_{41} must decrease as the voltage of the vehicle power supply increases.

In the second embodiment shown in FIG. 3b, the output frequency f_7 of the adder 69 can be fed directly to the solenoids 32, 33 of the injection valves. Thus, the frequency/time converter 70 is omitted as well as the divider 63. Thus, the electronic circuit arrangement in the second embodiment shown in FIG. 3b is of substantially simpler construction than in the first embodiment. On the other hand, the expenditure on mechanical parts is greater with continuously operating injection valves than with intermittently operating injection valves as used in the first embodiment. A valve whose flow cross section is proportional to the strength of the control current cannot be realised as simply as an intermittently operating valve which is either fully closed or fully open. Therefore, the overall expenditure is approximately equal in the two embodiments illustrated in FIG. 3a and FIG. 3b.

The individual structural components of the computing circuit illustrated in FIGS. 3a and 3b will be further described with reference to FIGS. 5a to 16b. However, to simplify this description, the mode of operation of a simple digital series multiplier will be first described with reference to FIGS. 4a and 4b.

The series multiplier illustrated in FIG. 4a comprises a divider-counter 71 and a divider gate 72. The divider-counter 71 is in the form of a three bit counter having three JK flip-flops (so-called "master-slave flip-flops") 73, 74, 75. The triggering inputs of the JK flip-flops are connected to a terminal 76 to which clock pulses f_0 are fed. The J,K inputs of the first JK flip-flop 73 are connected to a terminal 77. The J,K inputs of the second JK flip-flop 74 are connected to a first Q1 output of the first flip-flop 73. The J,K inputs of the third flip-flop 75 are connected to the output of an AND gate 78 whose two inputs are connected to the Q1 outputs of the first and second JK flip-flops 73, 74.

The terms "1 signal" and "0 signal" customary in digital technology are used in the following paragraphs. A "1 signal" is present when a point is at positive potential, while a point supplies an "0 signal" when it is at earth potential. The Q1 and Q2 outputs of the JK flip-flops are complementary to one another. This means that the Q2 output supplies an 0 signal when the Q1 output supplies a 1 signal.

The divider-gate 72 has a plurality of pulse train inputs supplied by input leads 79 to 83, and three binary number inputs 84 to 86. The highest digit of the binary number is designated MSB (most significant bit), and the lowest digit is designated LSB (least significant bit).

The divider-gate 72 itself comprises a decoding portion 87 to which the pulse train inputs 79 to 83 are connected, and a pulse synthesis portion 88 to which the binary number inputs 84 to 86 are connected. The decoding portion 87 includes three AND gates 89, 90, 91. The inputs of the first AND gate 89 are connected to the Q2 output of the first flip-flop 73 and to the Q1 output of the second flip-flop 74. The inputs of the second AND gate 90 are connected to the two Q2 outputs of the two flip-flops 73, 74. Finally, the inputs of the third AND gate 91 are connected to the output of the second AND gate 90 and the Q1 output of the third flip-flop 75.

The input of the pulse synthesis portion 88 includes three AND gates 92, 93, 94. The inputs of the fourth AND gate 92 are connected to the output of the third AND gate 91 and the first binary number input 84. In the same manner, the inputs of the fifth AND gate 93 are connected to the output of the first AND gate 89 and the second binary number input 85. The inputs of the sixth AND gate 94 are connected to the Q1 output of the first flip-flop 73 and the third binary number input 86. The outputs of the three AND gates 92, 93 and 94 are connected to inputs of an OR gate 95. The output of the pulse synthesis portion 88 is the output of an AND gate 96 whose two inputs are connected to the input terminal 76 and the output of the OR gate 95.

The mode of operation of the divider-counter 71 is known (see for example Dokter, Steinhauer: Digitale Electronik in der Messtechnik und Datenverarbeitung, 1969) and for this reason will be described only briefly with reference to FIG. 4b. When the J and K inputs of a JK flip-flop are connected to one another, one can differentiate between two operating states. When the two inputs carry 1 signals, as in the first JK flip-flop 73, the output signals at the Q1 and Q2 outputs change at the trailing edge of each clock pulse. This is shown by the two pulse trains f_0 and f_{73} in FIG. 4b. On the other hand, if the two interconnected J, K inputs carry an O signal, clock pulses cannot affect the switching state of the flip-flop. Thus, when a clock pulse f_0 arrives, the second JK flip-flop 74 changes its output signal only when a 1 signal is present at the Q1 output of the first flip-flop 73 for the duration of the clock pulse f_0 . Consequently, the three flip-flops 73, 74, 75 act as frequency dividers. The output frequency is halved at each further flip-flop, as is indicated in FIG. 4b.

The decoding portion 87 of the divider-gate 72 now serves to convert the output pulses of the individual flip-flops 73 to 75 in such a manner that, although their individual frequencies are retained, pulses of different frequency cannot overlap one another with respect to time. Therefore, the first AND gate 89 supplies a 1 signal only when a 1 signal appears at the Q1 output of the second flip-flop 74 and an O signal appears at the Q1 output of the first flip-flop 73. The pulse trains f_{73} , f_{89} and f_{91} in FIG. 4b illustrate the different frequency pulse trains whose pulses do not overlap with respect to time.

The pulse synthesis portion 88 of the divider-gate 72 enables the input clock pulses f_0 to be multiplied by an optional numerical factor which may be applied to the binary number inputs 84 to 86 in the form of a three-digit binary number. Since the individual pulses of the pulse trains f_{73} , f_{89} and f_{91} do not overlap one another with respect to time, these pulse trains can be added to one another in a simple manner in the OR gate 95. The

pulse trains which are to be added to one another can be selected by means of the AND gates 92, 93, 94.

In FIG. 4b, it is assumed in the case of the pulse trains f_{95} and f_{96} that the binary number 101 is present at the binary number inputs 84, 85, 86. Consequently, only the fourth AND gate 92 and the sixth AND gate 94 can supply 1 signals when the third AND gate 91 or the first flip-flop 73 at the same time supplies a 1 signal. The frequency of the pulse train f_{95} is now not yet equal to the sum of the two frequencies f_{73} and f_{91} , since some of the individual pulses of the input pulse trains of the OR gate 95 run into one another. The OR gate 95 supplies a single long output pulse from the instant t_3 up to the instant t_4 , although three input pulses are applied successively to its inputs.

An actual addition of the pulse trains f_{73} , f_{89} , f_{91} is obtained by strobing the pulse train f_{95} by means of the AND gate 96. The AND gate 96 utilizes the clock pulses f_0 as strobing pulses to reduce the duration of the pulses of the pulse trains f_{73} , f_{89} and f_{91} to the duration of the clock pulses f_0 . Therefore, three output pulses appear at the output of the AND gate 96 between the instants t_3 and t_4 . Consequently the output frequency of the AND gate 96 is equal to the sum of the two output frequencies of the pulse trains f_{73} and f_{91} .

It will be seen from the pulse train f_{96} that the individual pulses do not occur equidistantly, but are distributed with respect to time according to a predetermined pattern. However, the average pulse frequency per unit of time is constant if the unit of time under consideration is chosen to be sufficiently large. At the same time, the clock pulses, f_0 have been multiplied by a constant factor predetermined by the binary number 101. In the case under consideration, the factor is $\frac{1}{2} + \frac{1}{8} = \frac{5}{8}$.

In the series multiplier described with reference to FIGS. 4a and 4b, a small error is made when a frequency is multiplied by a binary number. This error is caused by the fact that the three-digit binary number has been produced as the result of a rounding-off. Thus, the maximum error is equal to half the value of the last binary digit. This maximum error amounts to $1/16 = 6.25\%$ in the three bit counter.

The three bit counter illustrated in FIG. 4a has been selected only as a simple example in order to simplify the description. In the individual embodiments described further below, eight bit counters are used in most cases, in which the maximum error is $1/512$, i.e. scarcely 0.2%. The series multiplier illustrated in FIG. 4a can also be used to multiply two frequencies when a frequency digital converter, as will be further described below with reference to FIG. 9a, is connected to the input sides of the binary number inputs 84 to 86. A series multiplier can also be used as a digital/frequency converter, since the frequency of the output pulses of the AND gate 96 is proportional to the binary number at the inputs 84 to 86. Since all the information concerning the operating state of the internal combustion engine is present in the form of variable pulse frequencies, such a series multiplier can be used universally for various structural groups of components of the circuits described with reference to FIGS. 3a and 3b.

The block circuit diagram of the first frequency/digital converter 57 and the first interpolator 58 is illustrated in FIG. 5a. The output frequency f_1 of the air flow meter 25-28 is present at the input terminal 56. This frequency is converted in the two stages 57, 58

into the output frequency f_{11} in which the characteristics of the internal combustion engine are taken into account. A first strobing stage 97 is connected to the input terminal 56. The output signals from the first strobing stage 97 and a frequency divider 99 are fed to a subtractor 98. An oscillation (hunting) suppressor 100 is connected to the subtractor 98, the two outputs of the oscillation suppressor being connected to the counting input z and the counting direction input d of a forward/backward counter 101.

The binary number output g_1 of the forward/backward counter 101 is connected to the binary number input of a first divider-gate 102. The first divider-gate 102 has two frequency outputs f_{12} and f_{13} which are both connected to inputs of a first adder 103. The output frequency f_{14} of the first adder 103 is fed to a second adder 105 by way of a second strobing stage 104. The output frequency $u \cdot f_{16}$ of the second adder 105 is present at the input of the frequency divider 99, u being the factor by which the frequency divider 99 divides the output frequency of the second adder 105.

The frequency inputs of the first divider-gate 102 are connected to frequency outputs of a central divider-counter 106. The central divider-counter 106 includes a decoding portion common to all the divider-gates connected thereto as described hereinafter. The circuit diagram of the central divider-counter 106 and the common decoding portion will be described further below with reference to FIG. 10. Furthermore, the central divider-counter 106 has a plurality of frequency outputs which are connected to inputs of a third adder 107 whose output frequency f_{15} is fed to the second adder 105 by way of a third strobing stage 108.

A pulse generator 109, which will be further described with reference to FIG. 11a, has its input supplied with clock pulses f_0 which may be taken, for example, from a quartz crystal oscillator (not illustrated). The outputs of the pulse generator 109 supply pulse trains f_{01} to f_{04} which have a small mark-to-space ratio and whose frequency equals one quarter of that of the clock pulses f_0 . These pulse trains f_{01} to f_{04} , which are out of phase with one another are fed to the individual strobing stages. The first, second and third strobing stages 97, 104 and 108 are controlled by the pulse trains f_{01} , f_{01} and f_{02} , respectively. Furthermore, the pulse generator 109 supplies a pulse train f_{05} . The pulse train f_{05} has the same frequency as the other pulse trains, but its mark-to-space ratio is equal to 1 : 1. The pulse train f_{05} is present at the counting input z of the central divider-counter 106.

The first interpolator 58 receives input signals from the central divider-counter 106 and input signals in the form of the binary number g_1 from the forward/backward counter 101. The binary number g_1 is fed to a "range" decoder 110 whose output signal can assume, in the present embodiment, five binary number states which correspond to five different frequency ranges of the input frequency f_1 .

Furthermore, a second divider-gate 111 has the frequency inputs of its pulse synthesis portion connected to the outputs of the central divider-counter 106 in the first interpolator 58. The binary number input of the second divider-gate 111 is connected to the output g_{12} of a "constant" store 112 whose input is connected to the output g_{11} of the "range" decoder 110.

A counting input z of a divider-counter 113 is connected to the frequency output f_{13} of the first divider-

gate 102 by way of a fourth strobing stage 114a which is controlled by the pulse trains f_{01} and f_{02} . A third divider-gate 114 is connected to the frequency outputs of the divider-counter 113. The output signal g_{13} from a 5 "slope" store 115 is present at the binary number input of the third divider-gate 114, the input of the store 115 being connected to the output g_{11} of the "range" decoder 110. A fifth strobing stage 112a, controlled by the pulse train f_{03} , is connected to the output of the second divider-gate 111, while a sixth strobing stage 113a, controlled by the pulse train f_{01} , is connected to the output of the third divider-gate 114. The outputs of the two strobing stages 112a, 113a are connected to two inputs of a fourth adder 116. The output of the fourth 10 adder 116 supplies the frequency f_{11} .

The mode of operation of the circuit illustrated in FIG. 5a will be described hereinafter with reference to FIGS. 5b and 5c. In the present embodiment, the subtractor 98 is in the form of an EXCLUSIVE OR gate.

20 The EXCLUSIVE OR gate 98 supplies an output pulse only when different signals are present at its two inputs. The output pulses of the first strobing stage 97 and the frequency divider 99 both occur during pulses of the strobing pulse train f_{01} . The EXCLUSIVE OR gate 98 does not produce a pulse when pulses of 1 signals are simultaneously supplied to the EXCLUSIVE OR gate 98 from the two stages 97, 99. Thus, the EXCLUSIVE OR gate 98 suppresses such pulses which appear simultaneously.

30 The oscillation suppressor 100 accomplishes two tasks. Firstly, it triggers the counting direction input d of the forward/backward counter 101. The counter 101 is to count in the forward direction pulses, coming from the first strobing stage 97 and to count in the backward direction the pulses, coming from the frequency divider 99. Secondly, the oscillation suppressor must supply a 35 counting pulse to the counting input z of the forward/backward counter 101 only when the EXCLUSIVE OR gate 98 has supplied two successive pulses in the same counting direction. Thus, the first pulse is always suppressed after a counting direction has been changed. This prevents the reading of the forward/backward counter 101 permanently fluctuating back and forth (hunting) by one binary digit when the frequency/digital converter 57 is in its steady state. Thus, hunting is effectively suppressed.

40 The counter outputs of the forward/backward counter 101 are fed as a binary number g_1 (air flow dependent) to the first divider-gate 102 where they are converted into a frequency f_{14} proportional to the counter reading g_1 . The frequency f_{14} appears at the output of the adder 103 as the sum of the two divider-gate output frequencies f_{12} and f_{13} . Since the frequencies f_{12} and f_{13} are non-coincidentally strobed, the adder 103 may be an OR gate whose mode of operation is the same as that of the OR gate 95 in FIG. 4a.

45 For the purpose of describing the mode of operation of the frequency/digital converter 57, the second adder 105 and the frequency divider 99 may be ignored in the first instance.

50 When the input frequency f_1 (representing rate of air flow) jumps abruptly in a positive direction at an instant t_5 (see FIG. 5b) the forward/backward counter 101 commences to count in a forward direction. Thus, 55 its reading g_1 increases rapidly. The central divider-counter 106 with the first divider-gate 102 is operated as a digital/frequency converter which converts the

60 65 When the input frequency f_1 (representing rate of air flow) jumps abruptly in a positive direction at an instant t_5 (see FIG. 5b) the forward/backward counter 101 commences to count in a forward direction. Thus, its reading g_1 increases rapidly. The central divider-counter 106 with the first divider-gate 102 is operated as a digital/frequency converter which converts the

counter reading g into the frequency f_{14} . This frequency f_{14} is now also fed to the subtractor (EXCLUSIVE OR gate) 98. The higher the counter reading g_1 , the smaller is the frequency differential $f_1 - f_{14}$ at the output of the subtractor 19. Therefore, the forward/backward counter 101 continues to count slower and slower in a positive direction until the frequency f_{14} has become equal to the input frequency f_1 . The forward/backward counter then stops at a reading g_1 which is proportional to the input frequency f_1 .

Thus, the counter reading g_1 does not follow the input frequency f_1 without a time delay, but approaches its final reading in accordance with an exponential function. When the frequency digital converter 57 is used in a servo-loop, it has the behaviour of a proportional servo having a time delay of the first order. The time delay T is determined by the number of stages in the forward/backward counter, by the magnitude of the input frequency f_1 , by the number of stages in the central divider-counter, and by the strobing pulse train f_{05} . The fewer the steps of the two counters 101, 106 and the higher the two frequencies f_1 and f_{05} , the shorter is the delay time T . Of course, a reduction in the number of counter stages impairs the accuracy of measurement. Furthermore, to ensure that the counter reading g_1 varies only slowly, the input frequency f_1 must be substantially smaller than the frequency of the strobing pulse train f_{05} . The series multiplier formed by the central divider-counter 106 and the dividegate 102 multiplies accurately only when the central divider-counter 106 has performed at least one complete counting cycle between two changes in the input reading g_1 . The binary number g_1 can be converted into the frequency f_{14} only after the central divider-counter 106 has completed a counting cycle.

The frequency divider 99 is provided in order simultaneously to fulfil the two requirements with respect to maximum accuracy of measurement (largest possible number of counter stages) and the shortest possible delay time T (f_{05} far greater than f_1). In the present embodiment, the frequency divider 99 is in the form of a six bit counter. Thus, the dividing factor u is 64. In the embodiment illustrated in FIG. 5a, the frequency of the pulse train $f_{05} = 768$ kHz. The maximum output frequency f_{14} of the dividegate 102 is 765 kHz and the maximum output frequency f_{16} of the frequency divider 99 is consequently 12 kHz. The above-mentioned requirement is fulfilled, since the input frequency f_1 is also of the order of magnitude of 10 kHz. The frequency of the pulse train f_{05} is substantially higher than the input frequency f_1 . Thus, a counter reading g_1 of the forward/backward counter 101 can be converted virtually instantaneously into a proportional frequency f_{14} . The delay time T is now influenced only by the value of the input frequency f_1 and by the capacity (number of digits) of the forward/backward counter 101.

Furthermore, in the embodiment illustrated in FIG. 5a, it has to be taken into account that the input frequency f_1 supplied by the LC oscillator 28, can assume values between 13 and 25 kHz according to the rate of air flow. In order to prevent a large proportion of the steps of the forward/backward counter 101 from being permanently occupied by the counting of the frequency of 13 kHz, which contains no information, the frequency of 13 kHz, occurring when the rate of air flow is 0, must be compensated for in the circuit. Therefore, a fixed frequency f_{15} , which is 13 kHz in the embodi-

ment, is added to the fed-back frequency f_{14} in the second adder 105. This "offset" frequency f_{15} of 13 kHz is formed from the output frequencies of the central divider-counter 106 in the third adder 107. Circuit details of the frequency/digital converter 57 will be described further below with reference to FIG. 9a.

Thus, the frequency/digital converter 57 includes a forward/backward counter 101 and, in the feedback circuit of the counter 101, a digital/frequency converter formed by the central divider-counter 106 and the first divider-gate 102. The output of the forward/backward counter 101 at the same time forms the output g_1 of the frequency/digital converter 57.

Referring to FIG. 5c, a curve 117 shows, for a specific internal combustion engine, the characteristic for the dependence of the quantity of fuel injected upon the rate of air flow in the inlet pipe. Thus the curve 117 also shows the desired dependence of the frequency f_{11} upon the input frequency f_1 . The interpolator 58 illustrated in FIG. 5a approaches the curve 117 by means of different straight line portions. For this purpose, the curve 117 is divided into different ranges I_1 to I_5 . In each individual range, the curve is approximated by a straight line whose equation is $f_{11} = Af_{13} + B$. The frequency f_{13} assumes zero value at the commencement of each range. A more detailed explanation will be given further below with reference to FIG. 9a.

Since all input values have to be reproduced by frequencies in the computing circuit in accordance with the invention, the interpolator 58 must include two fixed value stores in which the slopes A and the constants B are stored for the individual ranges I_1 to I_5 . Furthermore, the interpolator 58 must include a multiplier which forms the produce Af_{13} .

The input of the interpolator 58 is formed by the range decoder 110 which, for each range I_1 to I_5 , produces at its output a specific binary number characterising the relevant range. The circuit diagram of the range decoder will be described further below with reference to FIG. 12. The output of the range decoder 110 controls two stores, namely the constant store 112 for the vertical axis constants B and the slope store 115 for the slopes A of the straight portions.

In the manner already described above, the multiplier for the product Af_{13} comprises the divider-counter 113 and the third divider-gate 114. The counting input z of the divider-counter 113 processes only the output frequency f_{13} of the first divider-gate 102 which corresponds to the lowest digits (least significant bits) of the forward/backward counter 101. Thus, the zero point of the input frequency scale f_1 is shifted to the starting point of the relevant range for each individual range I_1 to I_5 . The higher digits of the forward/backward counter 101 determine the choice of the range by way of the range decoder 110, but have no effect upon the frequency f_{13} .

The output of the constant store 112 supplies a constant B which characterises the relevant range and which is multiplied by the pulse frequency f_{05} of the central divider-counter 106 in the second divider-gate 111. Thus, the output frequency f_{17} of the second divider-gate 111 is proportional to the constant B , while the output frequency f_{18} of the third divider-gate 114 is proportional to the product Af_{13} . The two output frequencies f_{17} and f_{18} are strobed by different pulse trains f_{03} and f_{01} in the two strobing stages 112a and 113a, so that the fourth adder 116 again may simply be in the

form of an OR gate (see the gate 95 in FIG. 4a). Thus, the output frequency f_{11} of the first interpolator 58 fulfills the equation $f_{11} = Af_{13} + B$ given above.

Now that the mode of operation of the frequency/digital converter 57 and the interpolator 58 has been described in the above paragraphs, the construction and mode of operation of the multipliers 64 and 65, the divider 63 and the frequency converter 68 will hereinafter be described with reference to FIG. 6, it being understood that the second frequency/digital converter 60 and the second interpolator 61 may be of the same construction as the first frequency/digital converter 57 and the first interpolator 58. The first multiplying input of the first multiplier 64 is formed by a second divider-counter 118 whose counting input z carries the output frequency f_{11} of the first interpolator 58. The frequency outputs of the second divider-counter 118 are connected to the frequency inputs of a fourth divider-gate 119. The output of the fourth divider-gate 119 at the same time forms the output of the first multiplier 64.

The output frequency f_3 of the pulse tachogenerator 41 present on the terminal 62 is fed to the input of a first synchronizing gate 120. A strobing pulse input 121 of the first synchronizing gate 120 carries the pulse train f_{03} which is taken from the pulse generator 109 illustrated in FIGS. 5a and 11a. In addition to the first synchronizing gate 120, the divider 63 includes a first forward counter 122 and a first final reading store 123. The outputs of the first forward counter 122 are connected to store inputs of the first final reading store 123. Two outputs of the first synchronizing gate 120 are connected to a reset input R of the first forward counter 122 and a transfer command input H of the first final reading store 123 respectively. A binary number output g_3 of the first final reading store 123 is connected to the binary number input of the fourth divider-gate 119 in the first multiplier 64.

In the embodiment of FIG. 3b the divider 63 is replaced by a frequency/binary converter which may comprise the forward counter 122 and the final reading store 123. In this case suitable strobing pulse trains are applied to the reset input R and the transfer command input H.

The second multiplier 65 includes a third divider-counter 124 whose outputs are connected to the frequency inputs of a fifth divider-gate 125. The counting input z of the third divider-counter 124 forms the first multiplying input of the second multiplier 65 and is connected to the output of the fourth divider-gate 119. The second multiplying input of the second multiplier 65 is formed by the binary number input of the fifth divider-gate 125. The latter is connected to the output g_5 of the decoder 48 whose output signal, as has been described above, is dependent upon the position of the butterfly valve.

The input terminal 66 serving to feed-in the voltage of the vehicle power supply, and the voltage/frequency converter 67 have already been described with reference to FIG. 3a. The input of the frequency converter 68 includes a second synchronizing gate 126 whose strobing input carries the pulse train f_{01} from the pulse generator 109. Furthermore, a second forward counter 127 is provided in the frequency converter 68. The pulse train f_{02} is fed to the counting input z of the second forward counter 177, while the reset input R is connected to an output of the second synchronizing gate 126. The outputs of the forward counter 127 are

connected to store inputs of a second final reading store 128. The transfer command input H of the second final reading store 128 is connected to a second output of the second synchronizing gate 126. The output of the second final reading store 128 is connected to the binary number input of a sixth divider-gate 129. The frequency inputs of the sixth divider-gate 129 are connected to the outputs of the central dividercounter 106 which has already been described above with reference to FIG. 5a.

The output of the fifth divider-gate 125 is connected to the first input of the adder 69 by way of a seventh strobing stage 130 controlled by the pulse train f_{03} , while the output of the sixth divider-gate 129 is connected to the second input of the adder 69 by way of an eighth strobing stage 131 controlled by the pulse train f_{04} . Since the output frequencies of the divider-gates 125, 129 are strobed by different pulse trains, an OR gate may again be used as the adder 69.

The mode of operation of the two multipliers 64 and 65 need not be described again in detail, since it has already been described above with reference to FIG. 4a. The two multipliers process a frequency and a binary number respectively. In the divider 63, the first forward counter 122 counts the frequency f_{21} proportional to the temperature of the engine block. After a pulse of the frequency f_3 proportional to the engine speed has arrived, the reading of the first counter 122 is transferred to the final reading store 123 by means of the first synchronizing gate 120, and the first forward counter 122 is then reset to 0 again by the first synchronizing gate 120. In the present embodiment, the frequency f_{21} is of the order of magnitude of 1000 kHz, while the frequency f_3 can assume values between 0.5 and 5 kHz. Thus, the first forward counter 122 counts to, for example 1000 during the period of the frequency f_3 which is proportional to the engine speed. This numerical value is transferred as a binary number to the final reading store 123 and remains at the binary number input of the fourth divider-gate 119 until the next engine speed pulse (f_3) arrives. Since the forward counter 122 always counts the temperature pulses (f_{21}) for one period only of the frequency f_3 and then is reset to 0 again, its final reading transferred to the final reading store 123 is inversely proportional to the frequency f_3 , i.e. to the speed of the internal combustion engine. At the same time, the final reading of the forward counter 122 is proportional to the frequency f_{21} which depends upon the temperature of the engine. Therefore, the final reading store 123 permanently carries a binary number which is proportional to the quotient f_{21}/f_3 . The construction of the circuit of the divider 63 will be described in further detail below with reference to FIGS. 14a and 14b.

The frequency converter 68 is also constructed as a simplified divider, since its output frequency is to be inversely proportional to the voltage of the vehicle power supply. Namely, the higher the voltage of the vehicle power supply, the shorter must be the injection period T_1 , since the injection valves open more rapidly as the voltage of the vehicle power supply increases. The output frequency f_3 of the voltage/frequency converter 67 is applied to the input of the second synchronizing gate 126 which controls the reset input R of the second forward counter and the transfer command input H of the second final reading store 128, as has been described above with reference to the divider 63.

Of course, in contrast to the divider 63, the second forward counter 127 is not supplied with a variable input frequency but with the fixed pulse train f_{02} as a counting frequency. Therefore, the binary number at the output of the second final reading store 128 depends only upon the voltage of the vehicle power supply and in inverse proportionality. It is multiplied by an additional constant factor E in the multiplier which is made up of the central divider-counter 106 and the sixth divider-gate 129, so that the equation $f_{41} = E/f_4$ applies to the output frequency f_{41} of the sixth divider-gate 129. The proportionality factor E can be chosen to obtain optimum adaptation to the actual injection valves used. The central divider-counter 106 in FIG. 6 used for multiplication by the constant factor E can obviously be that used in the circuit illustrated in FIG. 5a.

Only the frequency/time converter 70, included in the main components of the block circuit diagram illustrated in FIG. 3a remains to be explained with reference to FIG. 7. The input terminal of the frequency/time converter 70 is connected to the output of the adder 69 (see FIG. 6) which produces the frequency f_7 , and the input of the frequency/time converter 70 includes a frequency/digital converter 132 in which a forward/backward counter 133 is included as a sub-component. The frequency/digital converter 132 is of somewhat simpler construction than the frequency/digital converter 57 illustrated in FIG. 5a, since a constant "offset" does not have to be produced. The input frequency f_7 is fed to a first input of a subtractor 135 by way of a strobing stage 134 controlled by the pulse train f_{01} . The output of the subtractor 135 is connected to the input of an oscillation suppressor 136 whose two outputs are connected to the counting input z and the counting direction input d of the forward/backward counter 133. The outputs 137, 138, 139 of the forward/backward counter 133 are connected to the binary number input of a divider-gate 140a. The frequency inputs of the divider-gate 140a are connected to the outputs of the central divider-counter 106. The output of the divider-gate 140a is connected to a second input of the subtractor 135 by way of a frequency divider 141a and a strobing stage 142a controlled by the pulse train f_{02} .

The mode of operation of such a frequency/digital converter has already been described above with reference to FIG. 5a. It only remains to be mentioned that, in this instance also, the central divider-counter 106 of FIG. 5a can be used to control the divider-gate 140a so that there is a saving of structural components.

The output leads 137, 138, 139 of the forward/backward counter 133 are connected to setting inputs S of the backward counter 141 by way of a transfer gate 140 comprising AND gates 147, 148, 149. The backward counter 141 is illustrated by way of example as a three bit counter which includes three JK flip-flops 142, 143, 144. The pulse train f_{03} is fed to the triggering inputs of the three flip-flops 142 to 144 by way of an AND gate 145. The J, K inputs of the first flip-flop 142 are connected to one another and carry 1 signals. The Q2 output of the first flip-flop 142 is connected to the two inputs J, K of the second JK flip-flop 143. The Q2 outputs of the flip-flops 142, 143 are connected by way of an AND gate 146 to the interconnected J, K inputs of the third flip-flop 144.

The construction of the backward counter as a three bit counter is specified only as a simple example. Generally, counters having more steps will be used.

Furthermore, the setting inputs S of the three flip-flops 142 to 144 are connected to the respective AND gates 147, 148, 149. One input of each of the three AND gates 147, 148, 149 is connected to a switch 150 which is periodically opened and closed by a cam 151 in synchronism with the rotational speed of the crank-shaft of the internal combustion engine. The first inputs of the AND gates 147 to 149 carry a 1 signal when the switch 150 is closed.

The second inputs of the AND gates 147, 148, 149 are connected to output leads 137, 138, 139 of the forward/backward counter 133. The lowest digit (least significant bit, LSB) is associated with the AND gate 147, and the highest digit (most significant bit, MSB) is associated with the AND gate 149.

The Q₂ outputs of the three flip-flops 142, 143, 144 are connected to an AND gate 150a. The output of the AND gate 150a is connected by way of an inverter stage 151a to a second input of the AND gate 145 which is connected to the triggering inputs of the flip-flops 142 to 144. Furthermore, the output of the AND gate 150a is connected to the input K of a JK flip-flop 152. The J input of the flip-flop 152 is connected to the switch 150, while the triggering input is controlled by the pulse train f_{03} present also at the first input of the AND gate 145. The output of the flip-flop 152 is connected to the input of a power amplifier 153 which, by way of the terminal 34, controls the solenoid 32 which is illustrated as an example of one of the solenoids of the individual injection valves.

The course of a single injection operation with respect to time will be described hereinafter. It is assumed that the four injection valves of the internal combustion engine 20 (see FIG. 1) are all triggered at the same time, i.e. that their solenoids are connected in parallel with the solenoid 32 illustrated in FIG. 7. The common actuation of all injection valves is customary in simpler fuel injection systems. The switch 150 is closed by the cam 151 at a specific angle of the crank-shaft. A 1 signal thereby appears at the first inputs of the AND gate 147, 148, 149 and at the J input of the flip-flop 152. Therefore, at the trailing edge of the following strobing pulse of the pulse train f_{03} , the flip-flop 152 is triggered into the state in which a 1 signal is present at the Q1 output. The 1 signal at the Q1 output is fed to the solenoids 32 etc. of injection valves by way of the power amplifier 153, so that the injection valves are opened.

The additional setting inputs S of the individual JK flip-flops 142, 143, 144 of the backward counter 141 have precedence over the J, K inputs. Thus, with the closing of the switch 150, the reading of the forward/backward counter 133 is transferred to the individual stages (flip-flops 142 to 144) of the backward counter 141 by way of the AND gates 147 to 149. When, for example, the output lead 137 carries a 1 signal, the first flip-flop 142 is set such that a 1 signal is present at its Q1 output and an 0 signal is present at the Q2 output.

The counter 141 is constructed as a backward counter by virtue of the fact that, in contrast to the forward counter 71 illustrated in FIG. 4a, the Q2 outputs of the preceding stage are in each case connected to the J, K inputs of the following stage. The forward counter 71 illustrated in FIG. 4a and the backward

counter 141 illustrated in FIG. 7 in the form of integrated circuits are known.

When the reading of the forward/backward counter 133, which is proportional to the frequency f_7 , has been transmitted to the backward counter 141 after the switch 150 has closed, the backward counter 141 is triggered during the following period by the pulse train f_{03} by way of the AND gate 145 and the triggering inputs of the flip-flops 142 to 144. The outputs of the AND gate 150a carries an 0 signal in the first instance, since an 0 signal is always present at at least one of its inputs. Therefore, a 1 signal is applied to the second input of the AND gate 145 by way of the inverter stage 151a during the backward counting operation, this being the only thing which enables the counting operation to take place.

After a certain time, the backward counter 141 reaches the reading zero, i.e. its Q1 outputs carry the binary number 000 and its Q2 outputs carry the binary number 111. The AND condition of the AND gate 150a is now fulfilled and a 1 signal appears at its output. This 1 signal is inverted by the inverter stage 151a, so that an 0 signal appears at the second input of the AND gate 145. Thus, the AND gate 145 acts, together with the inverter stage 151, as an overrunning block to prevent the counter 141 counting back beyond zero. The backward counter 141 thus remains at the zero reading.

As soon as the zero reding is attained, a 1 signal is also present at the K input of the flip-flop 152. At the trailing edge of the following strobing pulse of the pulse train f_{03} , the flip-flop 152 is reset and the injection operation is terminated. Since the strobing frequency of the pulse train f_{03} remains constant, the duration of the injection pulse, supplied by the flip-flop 152, is proportional to the reading of the forward/backward counter 133 which is transferred to the backward counter 141 when the switch 150 closes. Thus, a frequency/time converter is realised by means of the circuit illustrated in FIG. 7. It may be pointed out here that, in the fifth embodiment illustrated in FIG. 8c, the backward counter 141 is controlled by a variable frequency and not by the constant frequency pulse train f_{03} . Thus, the injection period can be additionally influenced.

In the first embodiment, which up to now has been described with reference to FIGS. 1 to 7, the injection time T_1 is controlled in dependence upon the rate of air flow, the temperature of the engine block, the engine speed, the voltage of the vehicle power supply, and the position of the butterfly valve. In the first and second embodiments, the output signal of the oxygen measuring sensor 36 illustrated in FIG. 1 is not processed. On the other hand, as shown in FIGS. 8a to 8c, the other three embodiments, i.e. the third to fifth embodiments, are provided with circuit features which enable the injection time T_1 , or the quantity of fuel injected per unit of time, to be regulated in dependence upon the oxygen content of the exhaust gases. Practical experiments have shown that the servo-loop containing the oxygen sensor must include an integrating servo. Such use of an integrating servo is described in U.S. Pat. Application Ser. No. 259,157. Compared with the first two embodiments illustrated in FIGS. 3a and 3b, the only new feature of the three embodiments illustrated in FIGS. 8a to 8c is the servo-loop containing the oxygen measuring sensor 36. The control circuit for taking into account the other input quantities is of the same con-

struction as in the first two embodiments illustrated in FIGS. 3a and 3b and for this reason is not included in FIGS. 8a to 8c. The servo-circuit illustrated in FIGS. 8a and 8b may be combined with either of the two control circuits illustrated in FIGS. 3a and 3b. If the control circuits are to be used for continuously operating injection valves, the frequency/time converters 70 illustrated in FIGS. 8a and 8b have to be omitted.

The adder which supplies the output frequency f_7 of the control circuit illustrated in FIGS. 3a and 3b is again designated 69 in FIG. 8a. The output of the adder 69 is connected to a counting input z of a divider-counter 154. The outputs of the divider-counter 154 are connected to frequency inputs of a divider-gate 155. The divider-counter 154 and the divider-gate 155 together form a series multiplier 156. An output g_6 of a forward/backward counter 157 is connected to the binary number input of the divider-gate 155. The input of the forward/backward counter 157 is connected to an oscillaton (hunting) suppressor 158 whose outputs control the counting input z and the counting direction input d of the forward/backward counter 157.

The output frequency f_6 of the voltage/frequency converter 37 (see FIG. 1, output voltage of the oxygen measuring sensor 36) is fed by way of a strobing stage 159 controlled by the pulse train f_{04} to a subtractor 168 whose output is connected to the input of the oscillation suppressor 158. The desired value is given by a series multiplier 161 which comprises the central divider-counter 106 and a divider-gate 162. A "dividing factor" store 163 is connected to the binary number input of the divider-gate 162. The output frequency f_{61} of the divider-gate 162 is fed to the second input of the subtractor 160 by way of a strobing stage 164 controlled by the pulse train f_{03} .

In the third embodiment illustrated in FIG. 8a, the control circuit for processing the rate of air flow, the temperature of the engine block, the engine speed, the voltage of the vehicle power supply, and the positon of the butterfly valve, functions in the same manner as in the first embodiment illustrated in FIG. 3a. The frequency f_7 is indicative of the injection time T_1 determined by this control circuit. This injection time T_1 is further corrected by the air number servo-loop comprising the components 157 to 164. When using continuously operating injection valves, the corrected frequency f_{81} is fed directly to the solenoids 32, 33 as in the circuit illustrated in FIG. 3b.

If a catalytic after-burning device is connected to the exhaust gas collecting manifold 35 (see FIG. 1), it is advantageous to set the air number λ of the air/fuel mixture to a value of about 0.98, so that the catalytic reactor can operate in a reducing atmosphere. This desired value of the air number is given in the form of the frequency f_{61} and is fed to the input of the subtractor 160 designated "+". The frequency f_{61} is formed from the output frequencies of the central divider-counter 106, which can again be the central divider-counter 106 of FIG. 5a, by means of the series multiplier 161. The dividing factor store 163 supplies a constant binary number which serves as a multiplication factor. This binary number has to be adapted to the internal combustion engine being used, in order that the frequency f_{61} can accurately result in an air number $\lambda = 0.98$. The dividing factor store 163 could be adapted to supply different binary numbers under different operating states of

the internal combustion engine, so that different air numbers λ can be regulated.

The subtractor 160 serves to compare the desired value and actual value, since its input designed — is fed with the output frequency f_6 of the voltage/frequency converter 37 which depends upon the measured air number λ . The circuit arrangement of the oscillation suppressor 158 and the forward/backward counter 157 is the same as in the corresponding structural groups 100, 101 illustrated in FIG. 5a and will be described further below with reference to FIG. 9a.

The forward/backward counter 157 counts the individual pulses of the frequencies f_6 and f_{61} . The longer the two said frequencies differ from one another by a specific amount, the greater is the variation in the reading of the forward/backward counter 157. Therefore, the reading of the forward/backward counter 157 is proportional to the integral with respect to time of the difference between the frequencies f_{61} and f_6 . Thus, the integrating servo which, as mentioned above, is essential for stabilizing the servo-loop, is realised by means of the forward/backward counter 157. At the same time, any errors arising due to voltage drift of the output signal of the oxygen sensor are suppressed by the integrating servo.

The reading g_6 of the forward/backward counter 157 and the output frequency f_7 of the adder 69 (output frequency of the control circuit) are combined with one another multiplicatively as in the third embodiment illustrated in FIG. 8a. This is effected by the series multiplier 156 which, in the manner already described several times, comprises the divider-counter 154 and the divider-gate 155. The output frequency f_{81} of the multiplier 156 is converted into the injection time T_1 in the frequency/time converter 70.

In order to describe one particular regulating operation of the servo-circuit illustrated in FIG. 8a, it is now assumed, for example, that the control circuit supplies an output frequency f_7 which corresponds to an air number λ which is slightly too great, for example 1.05. Since the output voltage U of the oxygen measuring sensor (see FIG. 2b) has a falling characteristic, the frequency f_6 is smaller than the desired value frequency f_{61} for the air number $\lambda = 0.98$. Since the frequency f_6 is fed to the input of the subtractor 160 which is designated —, the forward/backward counter 157 now counts in a forward direction from its previous reading assumed when the air number was correct, so that the output frequency f_{81} of the multiplier 156 increases. Thus, the injection time T_1 becomes longer, and the air number λ is reduced, until the two frequencies f_6 and f_{61} assume the same value. The reading of the forward/backward counter 157 then remains constant.

In the fourth embodiment illustrated in FIG. 8b, an adder 165 is connected to the input of the frequency/time converter 70, one input of which adder is fed with the output frequency f_7 of the control circuit, if necessary by way of a strobing stage (not illustrated). As in the third embodiment illustrated in FIG. 8a, the subtractor 160 is provided for comparing the desired value with the actual value of the air number λ , while the oscillation suppressor 158 and the forward/backward counter 157 serve as an integrating servo. The reading g_6 of the forward/backward counter 157 is present at the binary number input of a divider-gate 166 whose frequency inputs are connected to the central divider-counter 106. The output frequency f_9 of the divider-

gate 166 is fed to the adder 165, again if necessary by way of a strobing stage (not illustrated).

Thus, the reading g_6 of the forward/backward counter 157 is converted into the frequency f_9 in the divider-gate 166. This frequency is added to the frequency f_7 and thus serves to correct the output signal from the control circuit. Thus, in contrast to the third embodiment, the binary number g_6 and the frequency f_7 are combined with one another additively and not multiplicatively in the fourth embodiment. Thus, the influence of the servo-loop for the air number λ is less than in the third embodiment. Thus, the third embodiment illustrated in FIG. 8a always has to be used when there is the possibility of the output frequency f_7 of the control circuit still being subjected to greater errors, for example if the counters used in the control circuit have only a few stages. On the other hand, it is advisable to use the fourth embodiment illustrated in FIG. 8b when the frequency f_7 has to be only slightly corrected.

In the fifth embodiment illustrated in FIG. 8c, the circuit construction of the structural components 160, 158, 157, 106 and 166 is the same as in the fourth embodiment illustrated in FIG. 8b. The output frequency f_9 of the divider-gate 166 is used directly as the backward counting or stepping frequency of the backward counter 141 in the frequency/time converter 70. Otherwise, the construction of the circuit of the frequency/time converter 70 is the same as is illustrated in and explained with reference to FIG. 7. An increase in the output frequency f_9 causes the backward counter 148 to count backwards more rapidly, so that the injection period T_1 is reduced. This behaviour is precisely the opposite to that in the fourth embodiment illustrated in FIG. 8b, so that the connections of the subtractor 160 have to be interchanged with one another. Thus, in the fifth embodiment illustrated in FIG. 8c, the frequency f_6 is fed to the input of the subtractor 160 which is designated +, while the frequency f_{61} is present at the input designated —. In the fifth embodiment, the binary number g_6 is again multiplicatively combined with the frequency f_7 as in the third embodiment. Since the frequency f_7 is fed directly to the frequency/digital converter 70 in the fifth embodiment, the circuit shown in FIG. 8c cannot be used to control continuously operating injection valves such as illustrated in FIG. 3b.

Now that the modes of operation of the five embodiments have been described, further circuit details of the embodiments will now be described with reference to FIGS. 9a to 16b. FIG. 9a shows the circuit diagram of the frequency/digital converter 57 illustrated in FIG. 5a. FIG. 9b shows the associated pulse graphs.

The input of the first strobing stage 97 includes a first D flip-flop (delay flip-flop) whose D input is connected to the terminal 56. The pulse train f_{01} is fed to a further input terminal 168. An inverter stage 169 is connected to the output side of the input terminal 168, and the triggering input of the first D flip-flop 167 is connected to the output of the inverter stage 169. The D input of a second D flip-flop 170 is connected to the Q1 output of the first D flip-flop 167. The Q1 output of the first flip-flop 167 and the Q2 output of the second flip-flop 170 are connected to two inputs of a NAND gate 171 which forms the output of the first strobing stage 97.

A further strobing stage (not illustrated in FIG. 5a) for strobing the output pulses of the frequency divider 99 is formed by a third D flip-flop 172. The D input of

the flip-flop 172 is connected to the output of the frequency divider 99, while its triggering input is connected to the output of the inverter stage 169. The Q2 output of the third flip-flop 172 and the output of the frequency divider 99 are connected to inputs of a NAND gate 173.

The subtractor 98 is in the form of an EXCLUSIVE OR gate. The inputs of the EXCLUSIVE OR gate 98 are connected to the outputs of the NAND gates 171, 173. The output of the EXCLUSIVE OR gate 98 is connected to an input of a NAND gate 174 whose second input is connected to the terminal 168. The output of the NAND gate 174 is connected to the input of the oscillation suppressor 100.

The input side of the oscillation suppressor 100 includes a fourth D flip-flop 175 whose D input is connected to the output of the NAND gate 173 and whose triggering input is connected to the output of the NAND gate 174. An input of a second EXCLUSIVE OR gate 176 is connected to the Q2 output of the fourth D flip-flop 175. The second input of the second EXCLUSIVE OR gate 176 is connected to the output of the NAND gate 173. A first input of a NAND gate 177 is connected to the output of the second EXCLUSIVE OR gate 176, while a second input is connected to the output of the NAND gate 174 by way of an inverter stage 178.

The forward/backward counter 101 is constructed as an integrated module. Such integrated counters are known. The counting input z is connected to the output of the NAND gate 177, while the counting direction input d is connected to the Q2 output of the fourth D flip-flop 175. The outputs of the forward/backward counter 101 are designated 1 to 8. The FIG. 1 indicates the lowest binary digit (least significant bit), while the highest binary digit (most significant bit) is designated 8.

The outputs 1 to 8 of the forward/backward counter 101 are connected to first input of respective AND gates 179 and 186. Output frequencies f_{121} to f_{128} of the central divider-counter 106 are fed to the second inputs of the AND gates 179 to 186. The lowest frequency f_{128} is present at the second input of the AND gate 179, while the highest frequency f_{121} is present at the input of the AND gate 186, and is thus associated with the most significant bit of the forward/backward counter 101. The producing of the frequencies f_{121} to f_{128} will be described below with reference to FIG. 10.

The outputs of the AND gates 179 to 182 are connected to inputs of a NOR gate 187. The output of the NOR gate 187 is connected to one input of an AND gate 188. The outputs of the AND gates 185 and 186 are connected to inputs of a NOR gate 189. The output of the AND gate 184 is connected to one input of an AND gate 190 and to the input of an inverter stage 191. The second input of the AND gate 190 is connected to a terminal 192 whose purpose will be explained below with reference to FIG. 12a. The outputs of the AND gates 183 and 190 are connected to inputs of a NOR gate 193. The output of the NOR gate 193 is connected to the second input of the AND gate 188. The gates 179 to 193 together form the pulse synthesis portion of the first divider-gate 102. The mode of operation of this pulse synthesis portion corresponds to that of the pulse synthesis portion 88 which has been described above with reference to FIG. 4a.

The outputs of the NOR gate 189, the inverter stage 191 and the AND gate 188 are connected to inputs of a NAND gate 103 which assumes the function of the first adder 103 illustrated in FIG. 5a. The output lead of the AND gate 188 carries the frequency f_{13} , while the output leads of the NOR gate 189 and the inverter stage 191 together carry the frequency f_{12} . The frequencies f_{12} and f_{13} have already been mentioned above with reference to FIG. 5a.

The two pulse trains f_{01} and f_{02} are fed to a NOR gate 195 by way of the terminal 168 and a further input terminal 194 respectively. The outputs of the AND gate 188 and the NOR gate 195 are connected to inputs of an AND gate 114a which assumes the function of the fourth strobing stage 114a described with reference to FIG. 5a. The output z_{113} of the AND gate 114 is connected to the counting input z of the divider-counter 113 which forms part of the first interpolator 58.

The output of the NAND gate 103 and the terminal 168 (frequencies f_{14} and f_{01}) are connected to inputs of a NAND gate 104 which assumes the function of a second strobing stage 104 illustrated in FIG. 5a.

The output frequencies $f_{124}, f_{126}, f_{128}$ of the central divider-counter 106 are fed to the three inputs of a NOR gate 107 which serves as the third adder 107 (illustrated in FIG. 5a). The NOR gate 107 has an additional blocking input 197 (strobe input). Such NOR gates having a strobe input are known in the form of integrated modules. The strobe input 197 is connected to the terminal 194. The strobe input 197 enables an AND function to be additionally realised in the case of the NOR gate 107 and thereby combines the third strobing stage 108 of FIG. 5a with the third adder 107. The outputs of the NOR gate 107 and the NAND gate 104 are connected to inputs of a NAND gate 105 which assumes the function of the second adder 105 illustrated in FIG. 5a and whose output is connected to the counting input z of the frequency divider 99.

In the present embodiment, an integrated six bit counter is used as the frequency divider 99. The highest binary digit (most significant bit) of the six bit counter is used as the output of the frequency divider 99. This results in a frequency step-down of 64:1 as described in the reference to FIG. 5a.

The time characteristics of the input frequencies f_1 and f_{16} and of the pulse train f_{01} are illustrated in FIG. 9b. Whilst FIG. 9b shows the leading edges of the pulses of frequency f_1 coincident with leading edges of pulses of the pulse train f_{01} , it will be appreciated that this will not normally be the case. However this is not of any consequence to the following description as a pulse of the frequency f_1 can only be transferred by pulses of the pulse train f_{01} . The output signals of further stages of the circuit illustrated in FIG. 9a are also shown and are designated f together with a suffix denoting the reference numeral of the relevant stage. The mode of operation of the first strobing stage 97, the EXCLUSIVE OR gate 98 and the oscillation suppressor 100 will first be described hereinafter with reference to FIG. 9b. A pulse of the input frequency f_1 commences at an instant t_5 (the time scale in FIG. 9b is different from that in FIG. 4b). This pulse f_1 is transferred to the output of the first D flip-flop 167 by the trailing edge of the next strobing pulse f_{01} . The pulse f_1 is transmitted to the second D flip-flop 170 at the trailing edge of the following strobing pulse f_{01} at the instant t_7 . The NAND gate 171 supplies an inverted output pulse f_{171} so long as the

input pulse f_1 has been transmitted to the first D flip-flop 167 but not yet to the second D flip-flop 170. Thus, the duration of the inverted output pulses of the NAND gate 171 is equal to the period of the pulse train f_{01} .

A D flip-flop is generally characterised in that the signal at its D input is transmitted to the Q1 output at the next triggering pulse.

A pulse of the feed-back frequency f_{16} (output frequency of the frequency divider 99) commences between the instants t_5 and t_7 , i.e. at the instant t_6 . This pulse is transmitted to the third D flip-flop 172 at the trailing edge of the next strobing pulse f_{01} i.e. at the instant t_7 , so that a 1 signal is present at the Q2 output of the flip-flop 172 during the following period. The NAND gate 173 produces an inverted output pulse in the period of time between the commencement of the pulse f_{16} and its transmission to the third D flip-flop 172, since its two inputs carry 1 signals during this period of time. Because the strobing stage 172, 173 connected to the output of the frequency divider 99 is of simpler construction than the first strobing stage 97, the duration of its output pulses is variable and is not equal to the period of the strobing frequency f_{01} . Thus, the NAND gate 174 described in the following paragraph is required.

The EXCLUSIVE OR gate 98 compares the two pulse trains f_{171} and f_{173} with each other. It produces a 1 signal at its output only when the two input signals are different. Since the pulse durations of the frequencies f_{171} and f_{173} are not equal, pulses can also appear at the output of the EXCLUSIVE OR gate 98 when the two input pulses f_1 and f_{16} appear simultaneously. This may be seen with reference to the pulses f_{98} appearing between t_5 and t_6 . The NAND gate 174 strobos the pulses coming from the EXCLUSIVE OR gate 98 by means of the strobing pulse train f_{01} i.e. an 0 signal can be present at the output of the NAND gate 174 only for the pulse duration of the pulse train f_{01} in the event that the EXCLUSIVE OR gate 98 simultaneously produces a 1 signal.

Since, referring to FIG. 9b, the first illustrated pulses of the respective frequencies f_1 and f_{16} both commence within one period of the pulse train f_{01} , and the flip-flops 167, 170 and 172 are triggered only by the pulse train f_{01} , these two first illustrated pulses f_1 and f_{16} must be regarded as being coincident. They are suppressed by the EXCLUSIVE OR gate 98 in cooperation with the NAND gate 174 as may be seen from the pulse train f_{174} in FIG. 9b.

Thus, those pulses of the frequencies f_1 and f_{16} which appear coincidentally are blocked in front of the input to the oscillation suppressor 100. Therefore, the forward/backward counter 101 cannot effect undesired counting operations. The oscillation suppressor 100 has the task, already mentioned above, of suppressing each first counting pulse of a counting direction in order to avoid periodic forward and backward counting of the forward/backward counter 101 by one digit. Such forward and backward counting could readily lead to control oscillation or hunting if the two frequencies f_1 and f_{16} are equal and their pulses appear alternately when the frequency/digital converter 57 is in its steady state. The Q2 output of the fourth D flip-flop 175 in the oscillation suppressor 100 receives the inverted output signal of the NAND gate 173 at the instant at which the output signal of the NAND gate 174

changes in a positive direction. At this juncture, it must be added that the triggering inputs of the D flip-flops 167, 170, 172 and 175 are triggered by the positive leading edges of the respective input pulses. Such positive-edge-controlled flip-flops are known in the form of integrated modules. Thus, the output signal of the fourth D flip-flop 175 is changed only when the output signal of the NAND gate 173 has changed. The follow-up of the output signal of the NAND gate 173 by the Q2 output of the fourth D flip-flop 175 is effected only at the leading edge of the next output pulse f_{174} . When the output signal of the NAND gate 173 changes, the same signals are present at the two inputs of the second EXCLUSIVE OR gate 176 until the instant of follow-up by the fourth flip-flop 175, since the complementary output signal Q2 of the fourth flip-flop 175 is being processed. Thus, during this period, the second EXCLUSIVE OR gate 176 supplies an 0 signal to the NAND gate 177, so that the latter cannot transfer counting pulses to the forward/backward counter 101. Different signals are present at the two inputs of the second EXCLUSIVE OR gate 176 only when the fourth flip-flop 175 has followed the output signal of the NAND gate 173 at the second pulse of a counting direction. The resultant 1 signal at the output of the second EXCLUSIVE OR gate 176 clears the path for the counting pulse from the NAND gate 174 to the forward/backward counter 101 by way of the inverter stage 178 and the NAND gate 177.

This operation will now be described in detail with reference to FIG. 9b. A second pulse of the input frequency f_1 commences at the instant t_8 . In the manner described above, this pulse effects an output pulse f_{98} of the first EXCLUSIVE OR gate 98, and, after an instant t_9 , an inverted output pulse f_{174} of the NAND gate 174. The output signal of the NAND gate 173, i.e. a 1 signal, is transmitted by the fourth D flip-flop 175 at the positive trailing edge of the inverted output pulse f_{174} , and the Q2 output of the flip-flop 175 therefore jumps to an 0 signal. The same 1 signal was present at the two inputs of the second EXCLUSIVE OR gate 176 before the output signal of the NAND gate 173 was transferred, so that the output of the EXCLUSIVE OR gate 176 produced an 0 signal. Therefore, the first counting pulse of the frequency f_1 , which would be counted in a positive direction cannot be transferred to the counting input z of the forward/backward counter 101 at the instant t_9 .

The operation is different at the next input pulse f_1 which commences at the instant t_{10} . This pulse also effects an output pulse of the first EXCLUSIVE OR gate 98 and, after an instant t_{11} , a negative output pulse of the NAND gate 174. Since no further input pulse has appeared between the instants t_9 and t_{10} , the output signal of the NAND gate 173 has not changed during this period of time. Different signals are present at the two inputs of the second EXCLUSIVE OR gate 176, and the second EXCLUSIVE OR gate 176 produces a 1 signal. The pulse f_{174} appearing after the instant t_{11} is inverted in the inverter stage 178 and, together with the output signal of the second EXCLUSIVE OR gate 176, effects an inverted counting pulse at the output of the NAND gate 177. This counting pulse appearing at the instant t_{11} is the first pulse to change the reading of the forward/backward counter 101, namely in the positive direction, since the 0 output signal of the fourth D flip-

flop 175 is simultaneously present at the counting direction input d .

Thus, the output signal of the fourth D flip-flop 175 simultaneously supplies the information about the counting direction of the forward/backward counter 101. Accordingly, the fourth D flip-flop 175 fulfills two tasks. Firstly, it ascertains whether the sign of the NAND gate 173 has changed between two counting pulses at the output of the NAND gate 174, i.e. whether two pulses of opposite signs have followed one another. Secondly, information is stored in the fourth D flip-flop 175 as to whether a pulse or a pulse interval of the frequency divider 99 exists, i.e. whether a positive or negative counting direction is required.

The switching operations which take place when two pulses f_{174} of different counting directions follow one another will be described hereinafter with reference to the second input pulse f_{16} which commences at the instant t_{12} . In the manner already described above, the input pulse f_{16} leads to a pulse f_{98} at the output of the first EXCLUSIVE OR gate and to an inverted pulse f_{174} which commences at the instant t_{13} at the output of the NAND gate 174. The (changed) output signal of the NAND gate 173 is transferred to the Q2 output of the fourth D flip-flop 175 at the positive trailing edge of the inverted pulse f_{174} . However, up to this transfer, 0 signals are present at the two inputs of the EXCLUSIVE OR gate 176 as a result of the change in the signal f_{173} , so that the EXCLUSIVE OR gate 176 also supplies an 0 signal and blocks the transfer of counting pulses. Consequently, the first pulse f_{174} which would be counted backwards is suppressed at the instant t_{13} after the two positive counting pulses (instants t_9 and t_{11}).

The reading of the forward/backward counter 101 varies less frequently as a result of the suppressing of alternating input pulses in the oscillation suppressor 100. Thus, the hunting in the servo-loop by one bit is suppressed when in the steady state. The reading of the counter 102 remains steady, since it has followed the input frequency f_1 .

At the same time, a time delay is effected, since stepping of the counter is suppressed until the second counting pulse in a given counting direction. However, this time delay can be maintained within the order of magnitude of a few hundred microseconds in the input frequency f_1 is sufficiently high. This small time delay is then not detrimental to the operation of the internal combustion engine.

After the description of the input circuit now follows the description of the function of the other components of the circuit diagram illustrated in FIG. 5a. The pulse synthesis portion of the first divider-gate 102 is of somewhat more complicated construction than the pulse synthesis portion described above with reference to FIG. 4a. This is due to the fact that the divider-gate 102 has to produce two output frequencies f_{12} and f_{13} , the second of which frequencies is further processed in the first interpolator 58. The NAND gate 103 fulfills the same task for the frequency f_{14} to be transmitted as the OR gate 95 illustrated in FIG. 4a. It combines the individual output frequencies of the frequency synthesis portion of the divider-gate 102 in an OR combination. That is to say, a NAND gate can also perform an OR operation since a 1 signal appears at its output as soon as an 0 signal is fed to one of the inputs. All the output signals of the AND gate 179 to 186, whose modes of operation correspond to the AND gates 92 to 94 illus-

trated in FIG. 4a, are fed to the NAND gate 103 by way of the gates 189, 190, 193, 187 and 188 and by way of the inverter stage 191, so that, according to the reading of the forward/backward counter 101, all the output frequencies f_{121} to f_{128} of the central divider-counter 106 can be contained in the output signals of the NAND gate 103.

The highest binary digits 8, 7, 6 of the forward/backward counter 101 are used for the range decoding, 10 while only the lowest five or six binary digits change within the individual ranges. In the first and second ranges I1 and I2, the lowest five binary digits of the forward/backward counter 101 have to be processed to obtain the output frequency f_{13} which is further processed in the interpolator 58. This will be further described below when discussing the range decoding with reference to FIG. 12a. The AND gate 190 effects the change-over from five to six binary digits. Alternatively, the two NOR gates 193, 187 could be combined 20 to form a single NOR gate, so that the AND gate 188 would not then be required. The example with two separate NOR gates 193, 187 has been selected, since only gates having a maximum of four inputs are commercially available in the form of integrated modules. 25 Thus, in cooperation with the AND gate 188 for the frequency f_{13} , the two NOR gates, 193, 187 fulfil the same task as the OR gate 95 illustrated in FIG. 4a.

In the case of a complicated division of the airflow-dependent frequency f_1 into ranges, it may prove necessary to provide a separate divider-gate, controlled by 30 the range decoder 110, to produce the frequency f_{13} . This is based on the requirement that the frequency f_{13} must assume zero value at the zero point of each individual range I1 to I5. In the embodiment illustrated in 35 FIG. 9a, this separate divider-gate has been reduced to the AND gate 190 which prevents the transmitting of the frequency f_{123} to the NOR gate 193 only within the first and the second ranges I1, I2. The change in the binary numbers at the output of the forward/backward counter 101 will be further explained below with reference to FIGS. 12a and 12b for the individual ranges I1 to I5.

The constant offset frequency f_{15} serves to compensate for the zero point frequency of the airflow meter 45 25, 28 (see FIG. 1) and is produced from the output frequencies f_{124} , f_{126} and f_{128} of the central divider-counter 106. The mode of operation of the NOR gate 107 also corresponds to that of the OR gate 95 illustrated in FIG. 4a. Controlling AND gates are not required, since only a constant frequency f_{15} has to be produced. The frequency f_{14} and the frequency f_{15} are strobed by different strobing frequencies f_{01} , f_{02} , the NAND gate 104 strobes the frequency f_{14} by means of the pulse train f_{01} . The strobe input 197 of the NOR gate 107 is controlled by the pulse train f_{02} , so that the NOR gate 107 can produce an 0 signal only for the duration of the pulses of the pulse train f_{02} . The function of the third strobing stage 108 of FIG. 5a is thus assumed by the strobe input 197. The NAND gate 105 again effects an OR operation of different 0 signals and, consequently, can be used as the second adder 105 (see FIG. 5a).

FIG. 9c shows a modified portion of the circuit diagram illustrated in FIG. 9a. This is intended to show that the strobing stage 97, the subtractor 98, and the oscillation suppressor 100 illustrated in FIG. 5a can also be realised as different circuit combinations. The

strobing stage 97 is constructed with the two D flip-flops 167, 170 and the NAND gate 171 in the same manner as in FIG. 9a. The strobing state connected to the output of the frequency divider 99 is supplemented by a further D flip-flop 172a, so that the construction of its circuit is the same as that of the first strobing stage 97.

Two AND gates 291, 292 are connected to these two strobing stages. One input of the AND gate 291 is connected to the output of the AND gate 173, and the other input of the AND gate 291 is connected to the output of the NAND gate 171 by way of an inverter stage 293. One input of the AND gate 292 is connected to the NAND gate 171, and the second input of the AND gate 292 is connected to the NAND gate 173 by way of an inverter stage 294.

A JK flip-flop 295 has its J input connected to the AND gate 291 and its K input connected to the AND gate 292. The pulse train f_{04} is fed to the triggering input of the JK flip-flop 295. The J input and the Q1 output of the JK flip-flop are connected to two inputs of an AND gate 296. The K input and Q2 output of the JK flip-flop 295 are connected to two inputs of an AND gate 297. The outputs of the two AND gates 296, 297 are connected to inputs of an OR gate 298.

The output of the OR gate 298 is connected to the counting input z of the forward/backward counter 101, while the output of the AND gate 297 is connected to the counting direction input d.

The circuit illustrated in FIG. 9c is somewhat more expensive than the corresponding circuit illustrated in FIG. 9a, although its mode of operation is simpler to understand. The mode of operation of the two strobing stages which are provided in the input of the circuit, and which include the flip-flops 167, 170 and 172a, 172 respectively, has already been described above with reference to FIG. 9a. The two NAND gates 171, 173 produce pulses which occur simultaneously with pulses of the strobing pulse train f_{01} . The pulse duration is equal to a period of the pulse train f_{01} . The effective 0 pulses at the outputs of the NAND gates 171, 173 are converted into 1 pulses by the inverter stages 293, 294.

1 pulses appearing simultaneously at the outputs of the inverter stages 293, 294 are suppressed by the AND gate 291. If, for example, the inverter stage 293 produces a 1 signal, the AND gate 291 can transmit this 1 signal only when the NAND gate 173 simultaneously produces a 1 signal. However, this is the case during the pulse interval of the NAND gate 173.

The JK flip-flop 295 assumes the function of the oscillation suppressor 100 in cooperation with the AND gates 296, 297. That is to say, the signals present at the J, K inputs of the JK flip-flop 295 are transmitted to the Q1, Q2 outputs only at the next strobing pulse. Therefore, the first pulse to be counted positively at the output of the AND gate 291 does not occasion a 1 signal at the output of the AND gate 296. 1 signals appear at the two inputs of the AND gate 296 only at the second pulse to be counted in the same direction. The output of the AND gate 297 at the same time carries an 0 signal which fixes the positive counting direction by way of the counting direction input d.

The function of the EXCLUSIVE OR gate 98 illustrated in FIG. 9a is assumed by the structural components 291 to 294 and 298 illustrated in FIG. 9c. Therefore, in the embodiment illustrated in FIG. 9c, the sub-

tractor 98 does not include an EXCLUSIVE OR gate provided as a separate structural component.

The central divider-counter 106 illustrated in FIG. 10 comprises an eight bit forward counter 198 and a decoder portion 199 which actually forms part of the individual divider-gates 102, 111, etc. However, the decoder portion 199 is common to all the controlled divider-gates. It is therefore considered to be part of the central divider-counter 106. The forward counter 198 has a counting input z to which the pulse train f_{05} is fed. Its eight binary digit outputs are designated 1 to 8.

The inverse outputs of the counter 198 are used, which outputs supply effective 0 signals.

The first output 1 is connected to an inverter stage 200 whose output produces the frequency f_{121} . The inverter stage 200 and the second output of the forward counter 198 are connected to inputs of a NOR gate 201 whose output supplies the frequency f_{122} . Furthermore, the first output 1 and the second output 2 are connected to a NAND gate 202. The output of the NAND gate 202 and the third output 3 of the forward counter 198 are connected to a NOR gate 203 whose output supplies the frequency f_{123} . The circuit combination is repeated periodically at the following outputs of the forward counter 198. NOR gates 204 to 208 are provided for supplying the respective frequencies f_{124} to f_{128} . The first input of each NOR gate 204 to 208 is connected to an output 4 to 8 of the forward counter 198. The second input of each NOR gate 204 to 208 is connected to an output of a NAND gate 209 to 213. An input of each NAND gate 209 to 213 is connected to that output of the counter 198 which precedes the output connected to the associated NOR gate 204 to 208. The second input of each NAND gate 209 to 213 is connected by way of an inverter stage 214 to 218 to the output of the preceding NAND gate 209 to 213.

The output frequencies f_{121} to f_{128} of the central divider-counter 106 are out of phase with one another with respect to time in the manner illustrated with reference to the frequencies f_{73} , f_{89} and f_{91} in the case of the simpler divider-counter illustrated in FIG. 4a. Thus, the individual pulses of the frequencies f_{121} to f_{128} directly follow one another, so that a strobing with one of the pulse trains has to be effected in the pulse synthesis portion of the associated divider-gate.

Like the frequency f_{73} illustrated in FIG. 4b, the first output frequency f_{121} has half the frequency of the pulse train f_{05} . The effective pulses at the outputs 1 to 8 of the counter 198 are 0 signal pulses, so that the frequency f_{121} includes effective 1 pulses after inversion in the inverter stage 200.

A 1 signal can appear at the output of the NOR gate 201 only when the second output 2 and the first output 1 simultaneously supply an 0 signal and a 1 signal respectively. In the same manner, the NOR gate 203 can supply a 1 pulse only when the third output 3 of the counter 198 supplies an 0 signal and the two outputs 1, 2 each supply a 1 signal. In this case, the output of the NAND gate 202 carries a second 0 signal which effects the 1 signal at the output of the NOR gate 203. Since the circuit construction is repeated periodically at the other points, the same conditions apply to the combining of the output frequencies of the counter 198 to produce the remainder of the output frequencies f_{121} to f_{128} of the decoder portion 199.

The circuit diagram of the pulse generator 109 indicated in FIG. 5a is illustrated in FIG. 11a. The input of

the pulse generator includes a two bit forward counter which comprises two JK flip-flops 219, 220. The two J,K inputs of the first flip-flop 219 carry a 1 signal, while the first Q1 output is connected to the two J,K inputs of the second flip-flop 220. The triggering inputs of the two flip-flops 219, 220 are connected to a terminal 221 to which the clock pulses f_0 are fed. In the present embodiment, the clock pulse frequency $f_0 = 3.072$ MHz is produced in a crystal oscillator (not illustrated) as previously mentioned.

Furthermore, the terminal 221 is connected to a respective input of two NAND gates 222, 223. The second input of the NAND gate 222 is connected to the first Q1 output of the second flip-flop 220, while the second input of the NAND gate 223 is connected to the second Q2 output of the flip-flop 220.

One input of each of two respective NOR gates 224, 225 is connected to the output of the NAND gate 222. The second inputs of the two NOR gates 224, 225 are respectively connected to the Q2 and Q1 outputs of the first JK flip-flop 219. In a similar circuit combination, two further NOR gates 226, 227, are connected to the output of the NAND gate 223 and respectively to the Q1 and Q2 outputs of the first JK flip-flop 219.

The pulse train f_{05} for controlling the central divider-counter 106 is taken directly from the second flip-flop 220. In the present embodiment, its frequency is 768 kHz and the mark-to-space ratio is 1 : 1. The pulse trains f_{01} to f_{04} have the same frequency but the mark-to-space ratio 1 : 7, the ratio of pulse duration to pulse interval being designated "mark-to-space ratio." The pulse trains f_{01} to f_{04} (see FIG. 11b) can be taken from the outputs of the NOR gates 227 to 224. The occurrence of these strobing pulses will be explained only briefly with reference to the fourth pulse train f_{04} . The output signal of the NOR gate 224 can be a 1 signal only when the NAND gate 222 and the second Q2 output of the first JK flip-flop 219 both supply an 0 signal. However, the NAND gate 222 can supply an 0 signal only when 1 signals are present at the terminal 221 and at the first Q1 output of the second JK flip-flop 220. Thus, each pulse train frequency has exactly the same pulse duration as the clock pulse train f_0 .

The circuit diagram of the range decoder 110 illustrated in FIG. 5a is shown in greater detail in FIG. 12a. Three output leads 228, 229, 230, connected to the highest digits of the forward/backward counter 101, are connected to inputs of the range decoder 110. The two output leads 229, 230 (7th and 8th digit of the forward/backward counter 101) are connected to two inputs of a NAND gate 231 whose output is designated I5. The third output lead 230 is connected directly to one of the inputs of a NAND gate 233, and the second output lead 229 is connected to the other input of the NAND gate 233 by way of an inverter stage 232, the output of the NAND gate 233 being designated I4. An input of a further AND gate 234 is connected directly to the lead 229, and the other input of the NAND gate 234 is connected to the lead 230 by way of an inverter stage 235. The output of the NAND gate 234 is designated I3.

The outputs of the two inverter stages 232, 235 are connected to inputs of a NAND gate 236 whose output is connected to the terminal 192 which has been already mentioned with reference to FIG. 9a. One input of a NAND gate 237 is connected to the terminal 192 by way of an inverter stage 238, and the other input of

the NAND gate 237 is connected to the first output lead 228 (6th digit of the forward/backward counter 101). One input of a NAND gate 239 is connected to the output of the inverter stage 238, and the other input of the NAND gate 239 is connected to the first output lead 228 by way of an inverter stage 240.

Reference may again be made to FIG. 5c for the purpose of describing the mode of operation of the circuit illustrated in FIG. 12a. The input frequency f_1 reduced by the constant offset frequency f_{15} is converted into a binary number in the forward/backward counter 101. The input frequency f_1 and the associated binary number at the output of the forward/backward counter 101 must now be divided into individual ranges I1 to 15 for the linear interpolation. In the present embodiment the division has been chosen such that the binary numbers at the output of the forward/backward counter 101 are correlated with the ranges I1 to I5 in the following manner:-

TABLE I

I1	:	00000000 to 00011111
I2	:	00100000 to 00111111
I3	:	01000000 to 01111111
I4	:	10000000 to 10111111
I5	:	11000000 to 11111111

It will be seen from Table I that only the three highest digits (most significant bits) of the forward/backward counter 101 have to be used for the range decoding. FIG. 12b shows the logic combinations which exist between the output signals of the forward/backward counter 101 and the individual ranges. The gating effected by the range decoder illustrated in FIG. 12a will readily be seen from these logic combinations. The signals present at the outputs 6, 7, 8 of the forward/backward counter 101 are designated C6, C7 and C8 in FIG. 12b. A dash above an individual signal or above a combination of signals represents an inversion. A dot between two signals signifies an AND operation.

The individual ranges are shown in the first column of FIG. 12b, the associated binary numbers according to Table I are shown in the second column, and the signal operations corresponding to the individual binary numbers are shown in the third column. It must be taken into account that the effective signals at the gate outputs designated I1 to I5 must be 0 signals. By way of example, the I5 signal must be an 0 signal when two 1 signals are present at the two outputs 7, 8 of the forward/backward counter 101. In this case, the operation shown in FIG. 12b is produced by the NAND gate 231 which first provides an AND operation between C8 and C7 then inverts this combination. The range I2 may be referred to as a more difficult example. In this instance, the logic operation given in FIG. 12b must be realised. In the first instance, the NAND gate 236 and the inverter stage 238 connected to the output thereof produce an AND operation between the signals C7 and C8 previously inverted in the inverter stages 232, 235. The output signal of the inverter stage 238, together with the non-inverted signal C6, are then fed to the NAND gate 237 which effects an AND operation with subsequent inversion. The other of the range signals I1 to I5 are produced in a corresponding manner.

The terminal 192 must supply an 0 signal when the frequency f_1 lies within one of the ranges I₁ or I₂, since only the five lowest digits of the forward/backward

counter 101 may then be taken into account for the purpose of synthesizing the frequency f_{13} (see FIG. 9a). The output signal of the 6th digit must not be transmitted by way of the AND gate 190. 0 signals, which are inverted in the inverter stages 232, 235, are present on the two output leads 229, 230 during the two ranges I1 and I2. It is precisely when 1 signals are present at the two inputs of the NAND gate 236 that the latter supplies the required 0 signal indicating whether the first or the second range exists.

The circuit diagram of the second divider-gate 111 and the constant store 112 (see FIG. 5a) is illustrated in FIG. 13. Again, only the pulse synthesis portion of the second divider-gate 111 is shown, since the output frequencies f_{121} to f_{128} of the central divider-counter 106 are processed in the pulse synthesis portion. The input of the pulse synthesis portion 111 includes eight AND gates 241 to 248 whose outputs are connected to inputs of an OR gate 249. A respective one of the frequencies f_{121} to f_{128} is fed to the first input of each AND gate 241 to 248. The output of the OR gate 249 is connected to an input of a NAND gate 112a which assumes the function of the fifth strobing stage 112a (see FIG. 5a). Therefore, the frequency f_{17} , whose pulses coincide with pulses of the strobing pulse train f_{03} , can be taken from the output of the NAND gate 112a.

The second input of the first AND gate 241 is connected to the I5 output of the range decoder 110 by way of an inverter stage 250. The second input of the second AND gate 242 is connected to the I4 output by way of an inverter stage 251. Furthermore the second input of the third AND gate 243 is connected to the output of a NAND gate 252 whose inputs are connected to the I5 and I3 outputs. The second input of the fourth AND gate 244 is connected to the I2 output terminal by way of an inverter stage 253. The fifth AND gate 245 is connected to the I4 and I1 terminals by way of an AND gate 254. The second input of the sixth AND gate 246 is connected to the output of the inverter stage 251. The second input of the seventh AND gate 247 is connected directly to the I5 terminal, while the second input of the eighth AND gate 248 is connected to the output of an AND gate 255 whose inputs are connected to the I1 and I3 terminals. The structural components 250 to 255 together form the constant store 112.

The circuit and the mode of operation of the pulse synthesis portion of the second divider-gate 111 does not differ from those of the pulse synthesis portion 88 illustrated in FIG. 4a. The OR gate 249 corresponds to the OR gate 95, while the AND gates 241 to 248 assume the function of the AND gates 92 to 94. The only difference resides in the fact that the forward counter 71 illustrated in FIG. 4a is in the form of a three bit counter, while the central divider-counter 106 is an eight bit counter.

The task of the constant store 112 is to store for each individual range I1 to I5 a specific binary number B1 to B5 (see FIG. 5c) which, in the relevant range, indicates the relevant value of the frequency f_{11} at the commencement of the range. There are many possibilities of realising such fixed value stores which have a plurality of input leads I1 to I5 and which provide a specific binary number whenever an 0 signal is present on one of the input leads. Only magnetic stores or stores having a diode matrix may be mentioned here. For the special case of a fuel injection system, the simplest method

has proved to be that of constructing the constant store 112 as a so-called "wired store". The different input leads are connected to the corresponding outputs simply by wires, as is shown, for example, by the wire between the I5 terminal and the AND gate 247. The wiring is generally simplified if inverter stages and gates are also provided between the inputs and the outputs, as is shown by the stages 250 to 255 in FIG. 13.

The range I2, in which an 0 signal is present on the I2 terminal and 1 signals are present on all other input terminals, may be selected by way of example. In this instance, reading from the top to the bottom, the binary number 0001111 shown in FIG. 13 is present at the output of the constant store 112. Thus, the output frequency f_{17} is composed of the frequencies f_{124} to f_{128} in the second range I2. The binary numbers associated with the other intervals may be read in a similar manner from the circuit diagram illustrated in FIG. 13. Of course, care has to be taken that the construction of the wired store 112 is accurately adapted to the internal combustion engine for which the embodiment under consideration is to be used. The required binary numbers at the output of the constant store 112 have to be ascertained experimentally for other internal combustion engines and other fuel injection systems.

Thus, the circuit details of the individual stages of the block circuit diagram shown in FIG. 5a have been described. The only stages not described in detail are the divider-counter 113, the divider-gate 114 and the "slope" store 115. The slope store 115 is constructed as a wired store in exactly the same manner as the constant store 112. The wiring has to be modified only so that the output leads g_{13} of the slope store 115 carry binary numbers which correspond to the individual slopes A1 to A5 (see FIG. 5c). The circuit diagram of a divider-counter with a divider-gate has already been described with reference to FIG. 4a, so that a fresh description of the circuit details of the divider-counter 113 and the divider-gate 114 is not required. The strobing stage 113a may again be an AND gate having one input connected to the output of the divider-gate 114 and the other input connected to the pulse generator 109.

The multipliers 64 and 65 shown in FIG. 6 also constitute combinations of structural components whose circuit details have already been described. It only remains to describe the divider 63 which is shown in FIG. 6 and whose detailed circuit diagram is illustrated in FIG. 14a. As already explained above with reference to FIG. 6, the divider 63 comprises the synchronizing gate 120, the forward counter 122 and the final reading store 123. The forward counter 122 is constructed in substantially the same manner as the forward counter 71 shown in FIG. 4a and is thus only briefly described again. Three JK flip-flops 256, 257, 258 form the essential structural components of the forward counter 122. The three flip-flops 256 to 258 have additional reset inputs R which are interconnected and form the reset input R of the forward counter 122. The counting input z is formed by the interconnected triggering inputs of the flip-flops 256 to 258. The interconnected J,K inputs of the first flip-flop 256 carry a 1 signal while the J,K inputs of the second flip-flop 257 are connected to the Q1 output of the first flip-flop 256. Finally, the J,K inputs of the third flip-flop 258 are connected to the output of an AND gate 259 whose inputs are connected to the Q1 outputs of the two flip-flops 256, 257.

The final reading store 123 includes three D flip-flops 260, 261, 262 whose Q1 outputs form the binary number output g_3 of the divider. The D inputs of the D flip-flops 260 to 262 are connected to the Q1 outputs of the JK flip-flops 256 to 258. The triggering inputs of the D flip-flops 260 to 262 are interconnected and form the transfer command input H of the final reading store 123. The input of the synchronizing gate 120 includes a first JK flip-flop 263 which is connected as a D flip-flop in that an inverter stage 264 is arranged between its J, K inputs. The output frequency f_3 of the pulse tachogenerator 41 (see FIG. 1) is fed to the J input of the first flip-flop 263. The J input of a second JK flip-flop 265 is connected to the Q1 output of the first JK flip-flop 263. The triggering inputs of the two flip-flops 263, 265 are interconnected and are connected to the input terminal 121 to which the pulse train f_{03} is fed. The inputs of a first AND gate 266 are connected to the terminal 121, the Q1 output of the first flip-flop 263, and the Q2 output of the second flip-flop 265. The inputs of a second AND gate 267 are connected to the Q1 output of the second flip-flop 265 and terminal 121. The output of the first AND gate 266 is connected to the transfer command input H of the final reading store 123, while the output of the second AND gate 267 is connected to the reset input R of the forward counter 122.

The mode of operation of the synchronizing gate 120 is explained with reference to FIG. 14b in which the individual pulse trains are designated f together with a suffix denoting the reference number of the associated stage. By way of example, it is assumed that a pulse of the frequency f_3 commences at an instant t_{14} . This pulse is received by the first flip-flop 263 at the trailing edge of the next following strobing pulse f_{03} . Thus, during the following period, the Q1 output of the flip-flop 263 supplies a 1 signal which is also present at the J input of the second flip-flop 265. The trailing edge of the next strobing pulse f_{03} (the second after the commencement of the pulse f_3) then also triggers the second flip-flop 265 such that a 1 signal is present at its Q1 output.

The two AND gates 266 and 267 are each controlled by a respective flip-flop output and the strobing pulse train f_{03} at the terminal 121. 1 signals are present at all three inputs of the first AND gate 266 when the second strobing pulse f_{03} appears at the instant t_{15} after commencement of the pulse f_3 , so that these 1 signals supply a 1 signal to the transfer command input H of the final reading store 123 for the duration of the strobing pulse f_{03} . The three D flip-flops 260 to 262 receive, with the positive leading edge of the pulse f_{266} the signals present at the outputs of the JK flip-flops 256 to 258. Thus, the final reading of the forward counter 122 is received in the final reading store 123. The second flip-flop 265 is set during the next following strobing pulse and its Q2 output supplies an O signal. Therefore, the AND gate 266 cannot supply any further transfer pulses.

1 signals are present at the two inputs of the second AND gate 267 during the next strobing pulse f_{03} which commences at the instant t_{16} . Therefore, the AND gate 267 supplies a pulse f_{267} which is fed to the reset R inputs of the flip-flops 256 to 258. The reset R inputs have precedence over the J, K inputs, so that all the flip-flops 256 to 258 are returned to their normal states after the instant t_{16} and their Q1 outputs supply O signals. The second AND gate 267 supplies further reset

pulses between the instants t_{16} and t_{17} , since, in contrast to the first AND gate 266, it has only two inputs. These additional reset pulses do not affect the mode of operation of the divider. During the period after the instant t_{17} , the forward counter 122, again commencing from zero, counts the pulses of the frequency f_{21} .

As has already been described above with reference to FIG. 6, the final reading g_3 of the forward counter 122 is proportional to the quotient f_{21}/f_3 , since, the higher the frequency f_3 , the fewer are the pulses f_{21} which can be counted by the forward counter 122 until the latter is reset.

The two flip-flops 263, 265 in the synchronizing gate are reset by the trailing edge of the next following strobing pulse f_{03} after the end of a pulse f_3 (at the instant t_{17}), so that the synchronizing gate 120 is again in its initial state. The circuit diagram of the synchronizing gate 120 shown in FIG. 14a is given only by way of example. A somewhat shorter time delay between transfer to the final reading store 123 and the resetting of the forward counter 122 results if the two flip-flops 263 and 265 are triggered by different pulse trains, i.e. f_{03} and f_{04} respectively (see FIG. 11b). It is a simple matter to elaborate upon the circuit illustrated in FIG. 14a to form an eight bit counter by increasing the number of stages in the counter 122 and of the store 123.

FIG. 15 shows a portion of the circuit diagram of the decoder 48 which produces different binary numbers in dependence upon the position of the butterfly valve. The two switches 46,47 are in the form of change-over switches, one fixed contact of each switch being connected by way of a respective resistor 268 and 269 to a terminal 270 to which a 1 signal is applied. The other two fixed contacts are connected to earth, i.e. they receive an O signal. The movable contacts of the change-over switches 46,47 are connected to an input of a respective AND gate 271,272. The first input of a further AND gate 273 is connected to the terminal 270. The outputs of the three AND gates 271 to 273 are connected to inputs of an OR gate 274 whose output supplies one digit of the binary number g_5 .

An O or a 1 signal is applied to the free inputs of the AND gates 271 to 273 according to the value which the binary digit at the output of the OR gate 274 is to assume. The binary number g_5 has three digits in the present embodiment, so that three circuit arrangements, as illustrated in FIG. 15, also have to be provided in parallel.

Of course, all the AND gate 271 to 273 may be omitted in the practical embodiment of the circuit illustrated in FIG. 15. An AND gate may be entirely omitted if an O signal had to be applied to its free input. Conversely, an AND gate can be replaced by a wire connection if a 1 signal is applied to its free input. It will be readily seen from this embodiment how one proceeds from a desired circuit combination to a wired store in which binary numbers are produced by circuit connections. The wired store, which can be constructed in accordance with FIG. 15, may be replaced by a store having a diode matrix.

FIG. 16a shows the circuit diagram of the voltage/frequency converter such as may be used for the components 39, 37 and 67 shown in FIGS. 1 and 3a. Such a voltage/frequency converter may also be referred to as a simplified analog/digital converter, since it converts an analog input voltage into digital information, i.e. a pulse frequency. The circuit illustrated in FIG. 16a

comprises a voltage controlled oscillator whose input includes a first operational amplifier 275. The inverting input of the first operational amplifier 275 is connected to an input terminal 277 by way of a resistor 276 and its non-inverting input is connected by way of a resistor 278 to the tapping of a voltage divider comprising two resistors 279, 280. An integrating capacitor 281 is located between the output and the inverting input in the feedback path of the operational amplifier 275. The emitter-collector path of an n-p-n transistor 282 serving as a semi-conductor switch is connected in parallel with the integrating capacitor 281.

The inverting input of a second operational amplifier 283 is connected to the output of the first operational amplifier 275 by way of a resistor 284. The non-inverting input of the second operational amplifier 283 is connected by way of a resistor 285 to the tapping of a voltage divider comprising two resistors 286, 287. The output of the second operational amplifier 283 at the same time forms the output of the voltage/frequency converter. Furthermore, this output is connected to the base of the transistor 282 by way of a resistor 288.

The two voltage dividers 279, 280 and 286, 287 are each connected between a positive lead 289 and a negative lead 290. The base of the transistor 282 is connected to the negative lead 290 by way of a capacitor 291.

The first operational amplifier 275 and the integrating capacitor 281 together form an integrator. When the input voltage, which is applied to the terminal 277 and which is to be converted into a proportional frequency, is higher than the voltage tapped from the voltage divider 279, 280, the operational amplifier 275 integrates in a negative direction with a slope which is proportional to the difference between the voltages at the two inputs of the operational amplifier 275. At the instant t_{18} (FIG. 16b) the voltage at the output of the first operational amplifier 275 becomes lower than the voltage tapped from the voltage divider 286, 287. Since the second operational amplifier 283 has a high internal amplification factor and has no feedback, it operates as a comparator. Thus, its output voltage jumps abruptly in a positive direction at the instant t_{18} .

The transistor 282 thus becomes conductive and discharges the charged integrating capacitor 281 again. The capacitor 291, in cooperation with the resistor 288, forms a time delay circuit which ensures that the transistor 282 remains conductive for an adequate period of time in order fully to discharge the capacitor 281. After the integrating capacitor 281 has been discharged, the output voltage of the first operational amplifier 275 is again higher than the voltage tapped from the voltage divider 286, 287, so that the second operational amplifier 283 again produces an 0 signal. The entire operation is then repeated periodically.

The frequency is dependent upon the slope with which the integrator 275, 281 integrates in a negative direction. Since, as already mentioned, this slope is dependent upon the input voltage at the terminal 277, the output frequency f_{283} is proportional to the difference between the voltage at the terminal 277 and the voltage tapped from the voltage divider 279, 280. Thus, by virtue of this circuit illustrated in FIG. 16a, a voltage/frequency converter is realised by simple means.

All the components of the circuits illustrated in FIGS. 5a and 6 have now been described. As already explained, the frequency converter 68 is a simplified ver-

sion of a divider and can thus be constructed in accordance with FIG. 14a. The frequency/digital converter 132 illustrated in FIG. 7 can be constructed in accordance with FIG. 9a, there being no need to provide the NOR gate 107 which serves to produce the constant offset frequency f_{15} . The embodiments illustrated in FIGS. 8a to 8c include, in addition to the components of the first embodiment, only further multipliers, subtractors, adders and strobing stages. The circuit diagrams of such components have been described in detail with reference to the first embodiment.

The input quantities are fed to the coupling circuit as digital information. In general, a frequency, and not a binary number, has been selected to represent the digital information to be processed. This reduces, on the one hand, the number of the required input leads which lead from the various measuring points to the computing circuit. On the other hand, the measuring frequencies are varied only slightly by individual interference pulses, while, during the transmission of binary numbers, there would be the risk that the same interference pulse would interfere with all the transmission leads and simultaneously thus falsify the binary number to a considerable extent. Thus, the problem of interference, which is particularly important in motor vehicle electronics, is substantially solved in an optimum manner.

Furthermore, the individual components of the computing circuit include only logic gates, trigger stages, counters and store circuits. Thus, there is no need for any adjustments when manufacturing the computing circuits, so that, compared with analog computing circuits, manufacture is substantially simplified and reduced in cost.

Superficially, the individual circuit diagrams might appear to be substantially more complicated than corresponding circuit diagrams of analog computing circuits. Of course, this does not in any way mean that the entire digital incremental computing circuit takes up more space, and is more expensive to manufacture, than an equivalent analog computing circuit, for it is possible to make extensive use of components which are to a considerable extent in the form of integrated circuitry. Thus, for example, a single integrated module, which includes a six bit divider counter together with the associated divider-gate, can be used for the divider-counter 113 and the divider-gate 114 in the circuit shown in FIG. 5a. When manufacturing larger quantities, it is readily possible, for example, to accommodate a complete frequency/digital converter in a single integrated module.

The multiple use of the central divider-counter 106 also results in a substantial simplification of the construction of the circuit. At this juncture, it should be emphasised that the circuit diagrams shown in FIGS. 9a to 16a are to be considered only by way of example. It is readily possible to use different multiplier circuits which permit the multiplication of two digital values. The above description also gives different embodiments for the strobing stages which can be interchanged according to requirements. It may also prove to be advantageous to use more than four different pulse trains for triggering the strobing stages.

The digital incremental computing circuit operates to a large extent rather like an analog computing circuit. In other digital computing circuits it is customary to repeatedly compute the result, i.e. the injection time, from the individual input quantities. This method is

very accurate and also enables rapid variations in the input quantities to be detected in a reliable manner. However, a considerable expenditure on circuitry has to be accepted, an expenditure which increases the more rapidly the circuit is to operate. An analog computing circuit continuously varies its output value when the input quantities vary. The digital incremental computing circuit also uses this latter method, at least in so far as the highest digits of the binary numbers (most significant bits) are concerned. This will be seen particularly clearly with reference to the frequency/digital converter 57 illustrated in FIG. 5a. The forward/backward counter 101 maintains its reading provided that the input quantity, i.e. the frequency f_1 , does not vary. Thus, in contrast to other digital computing circuits, the forward/backward counter does not repeatedly count from zero onwards until it has reached its reading. Thus, counting time can be saved, or the counting frequency can be reduced. Of course, the digital incremental computing circuit operates substantially more accurately than a corresponding analog computing circuit, since the counting result of the forward/backward counter 101 is accurately computed to 8 bits. This corresponds to an accuracy of 0.4 percent, which can scarcely be achieved with analog computing circuits in motor vehicles. On the other hand, the digital incremental computing circuit technology enables the forward/backward counter to be provided with even more counting steps, thus further increasing the accuracy.

In general, the dependence of the computed result, i.e. the injection period T_1 , or the quantity of fuel injected per unit of time, upon the individual input quantities, such as rate of air flow and temperature of the engine block, is not linear. The corresponding interrelationships have to be determined experimentally for each individual internal combustion engine and plotted as fields of characteristics. The individual non-linear fields of characteristics are simulated in the interpolators. When taking into account the voltage of the vehicle power supply, it has proved to be unnecessary to provide a special interpolator, since the total influence of the voltage of the vehicle power supply on the injection period or the injection quantity is less than 10 percent. Thus, the frequency converter 68 simulates a linear characteristic, without the possibility of a greater error in the injection period occurring.

The shape of the characteristic is stored in the individual interpolators by the constant store and the slope store, and by the range decoder. The particular characteristic is approximated by adjoining straight portions by the range division and by the correlation of constant values and slope values with the individual ranges. The accuracy is better than 0.5 percent.

The first two embodiments illustrated in FIGS. 3a and 3b permit control of only the injection period and the injection quantity respectively. Therefore, it is necessary to design the control circuits illustrated in FIGS. 3a and 3b for the greatest possible accuracy, if it is desired to obtain satisfactory cleanliness of the exhaust gases at the same time as controlling the injection. In the three embodiments illustrated in FIGS. 8a to 8c, the demands on the accuracy of the control circuit are not so great, since a value of the frequency f_7 which has been inaccurately calculated in the control circuit can still be corrected by the air number servo-loop. Thus, in the embodiments illustrated in FIGS. 8a to 8c, the expenditure on circuitry is only very slightly greater

than in the first two embodiments. In any event, cleaner exhaust gases can be obtained with the last three embodiments than with the first two embodiments.

The foregoing disclosure describes transducers, for example the air flow transducers (25-27) which provide signals of varying amplitudes, for example a voltage variable output, to which an oscillator (28) is connected, providing a variable output frequency in accordance with voltage variation. The variable output frequency is then converted into digital form in frequency/digital converter (57). The feature of the invention is particularly suitable for use with internal combustion engines subject to widely varying operating conditions, such as occur in mobile or automotive installations.

15 The function of providing digital output signals representative of an input parameter may be combined in one element, and some transducers have been proposed which provide direct digital read out. In such case, the function of transducers - oscillator - converter 20 is then combined in a single unit. For most mobile and automotive applications, the oscillator -frequency/digital converter provides, in simple and effective manner, trouble-free digital output representative of the various parameters to be transduced.

25 Various changes and modifications may be made within the scope of the inventive concept, and features disclosed and described with any one embodiment may be equally applied to either embodiments, within the scope of the invention.

30 We claim:

1. In combination with an internal combustion engine having an induction pipe, a control device for controlling at least one solenoid (32, 33) operated fuel injection valve (29, 30) in dependence upon the rate of air flow to the engine through the induction pipe, comprising

35 an air flow meter (25, 26) to be arranged in the induction pipe of the engine; an oscillator (28), the frequency of which is controlled by the air flow meter (25, 26) to provide an oscillator output signal whose frequency is a function of the rate of air flow; a frequency digital converter connected to receive the oscillator output signals and providing digital signals representative of the frequency of the oscillator, and hence of the rate of air flow; and a digital computing circuit having an input connected to receive the digital signals and having an output connected to and controlling the solenoid (32, 33) of the fuel injection valve (29, 30), said computing circuit comprising

a digital differential analyzer whose input is responsive to said digital signals derived as a function of frequency of the oscillator. and at least one interpolator (58, 61) having stored therein simulated operating characteristics of the internal combustion engine over its operating range to modify the digital signals passing through said computing circuit in accordance with said simulated operating characteristics of the combustion engine.

60 65 2. A control device as claimed in claim 1, for an engine having at least one intermittently operating fuel injection valve (29, 30) for metering the fuel, in which the computing circuit includes a frequency/time converter (70) connected to and controlling the solenoid (32, 33) of the fuel injection valve and being respon-

sive to the output frequency (f_{11}, f_{21}) of the interpolator (58, 61).

3. A control device as claimed in claim 2, in which said frequency/time converter (FIG. 7: 70) comprises a frequency/digital converter (132), a backward counter (141) and a transfer gate (140) connecting the output of the frequency/digital converter (132) to the input of the backward counter (141).

4. A control device as claimed in claim 3, in which the backward counter (141) comprises a series combination of a plurality of JK flip-flops (142-144) to whose triggering inputs a stepping pulse train (f_{03}) is applied.

5. A control device as claimed in claim 4, comprising a first AND gate (150);

wherein the Q2 outputs of the JK flip-flops (142-144) are connected to inputs of the AND gate (150) whose output is connected by way of an inverter (151) stage to one input of another AND gate (145) to whose other input is applied the strobing pulse train (f_{03}), and whose output is connected to the triggering inputs of the JK flip-flops (142-144).

6. A control device as claimed in claim 3, comprising a power amplifier (153) having its output connected to the inputs of the solenoids (32, 33) serving to actuate the fuel injection valves (29, 30);

25 a JK flip-flop, (152) the input of the power amplifier (153) being connected to the output of the JK flip-flop (152), said JK flip-flop (152) being controlled by the backward counter.

7. A control device as claimed in claim 4, in which the transfer gate (140) comprises a group of AND gates (147-149) of equal number to the number of steps of the backward counter, one input of each of the AND gates of the group being connected to a signal representative of engine speed; and means (150) operable in synchronism with the rotational speed of the crankshaft of the internal combustion engine generating said speed signal.

8. A control device as claimed in claim 7, comprising a JK flip-flop (152) having its J input connected to the speed signal, its K input connected to the output of the AND gate (150), and the strobing pulse train (f_{03}) is applied to the triggering input thereof of the JK flip-flop.

9. A control device as claimed in claim 2, in which the frequency/time converter (FIG. 7: 70) comprises a frequency/digital converter (132) which includes a forward/backward counter (133) and a feedback loop containing a digital/frequency converter (140, 141, 142) arranged between the binary number output and the counting input (z) of the forward/backward counter (133) (FIG. 7).

10. A control device as claimed in claim 9, in which the digital/frequency converter is a series multiplier and includes a divider-counter (106) and a divider-gate (140) connected to the outputs of the divider-counter (106).

11. A control device as claimed in claim 10, further comprising a subtractor (135) having its output connected to the counting input (z) of the forward/backward counter (133) and its input connected to the input signal (f_7) to the frequency/digital converter (132), and the output frequency of the divider-gate (140).

12. A control device as claimed in claim 11, in which a frequency divider (141) is arranged between the output of the divider-gate (140) and the subtractor (135).

13. A control device as claimed in claim 11, in which an oscillation suppressor (136) is arranged between the subtractor (135) and the counting input (z) of the forward/backward counter (133) the oscillation-suppressor also being connected to and controlling the counting direction input (d) of the forward/backward counter (133).

14. A control device as claimed in claim 11, comprising first and second strobing circuits (134, 142), wherein said input signal (f_7) and said output frequency of the divider gate (140) are applied via the respective first and second strobing stage (134, 142) to the inputs of the subtractor (135).

15. A control device as claimed in claim 7, wherein the frequency/digital converter (132) comprises a forward/backward counter (133), in which the binary output of the forward/backward counter (133) is connected to the second inputs of the group of AND gates (147-149).

16. A control device as claimed in claim 1, for an engine having a continuously operating fuel injection valve (29, 30) for metering the fuel, in which the output of said interpolator (58, 611) at least in part determines energization of the solenoid (32, 33) which controls the position of the fuel injection valve.

17. A control device as claimed in claim 1, further comprising a temperature sensor (38) placed in thermal contact with the internal combustion engine (20) and a voltage/frequency converter (39) whose input is connected to the electrical output of the temperature sensor (38), and wherein the computing circuit includes a second frequency/digital converter (60) whose input is connected to the output of the voltage/frequency converter (39).

18. A control device as claimed in claim 17, comprising a second interpolator (61) connected to the output of the second frequency/digital converter (60).

19. A control device as claimed in claim 2, comprising a pulse tachogenerator (41) driven by the crankshaft (40) of the internal combustion engine (20) and providing a speed signal (f_3);

wherein the computing circuit is connected to process the output of the interpolator (58) and the output (f_3) of the tachogenerator (41) to obtain a derived signal dependent upon both the air quantity and the engine speed, said derived signal being fed at least indirectly to said frequency/time converter (70).

20. A control device as claimed in claim 19, in which the computing circuit comprises a divider (63), one of whose inputs is connected to the tachogenerator (f_3) so that the output frequency of the divider is dependent upon the reciprocal of the engine speed, and a multiplier (64), having two inputs to which the outputs of the interpolator (58) and the divider (63) are respectively connected so that said derived signal appears at the output of said multiplier (64).

21. A control device as claimed in claim 18, wherein the computing circuit includes a frequency/time converter (70) responsive to the output frequency (f_{11}, f_{21}) of the interpolator, and connected to and controlling the solenoid of the fuel injection valve, further comprising

a pulse tachogenerator (41) adapted to be driven by the crankshaft (40) of the internal combustion engine (20), and providing a speed signal (f_3); wherein the computing circuit comprises

10 a divider (63) having two inputs to which the second 5 interpolator (61) and the tachogenerator (41) are respectively connected,

and a multiplier (64) having two inputs to which the 15 outputs of the first interpolator (58) and the divider (63) are respectively connected, the output 10 of said multiplier (64) being connected at least indirectly to the input of the frequency/time converter (70) whose output controls the solenoid (32, 33) of the fuel injection valve (29, 30).

22. A control device as claimed in claim 21, in which the divider (63) comprises (FIG. 14a)

a forward counter (122), a "final reading" store (123) whose inputs are connected to the binary number output of the forward counter (122);

20 and a synchronizing gate (120), a first output of which is connected to a reset input (R) of the forward counter (122) and a second output of which is connected to a "transfer command" input (H) of the final reading store (123), the output frequency (f_{21}) of the second interpolator (61) being applied to the counting input (z) of the forward counter (122) and the output frequency of the pulse tachogenerator (41) being applied to the 25 input of said synchronizing gate (120).

23. A control device as claimed in claim 22, in which the synchronizing gate (120) has a synchronizing input (121) to which a strobing pulse train (f_{03}) is applied.

24. A control device as claimed in claim 22, in which 35 said synchronizing gate (120) comprises

first and second JK flip-flops (263, 265), the output 40 frequency (f_3) of the tachogenerator (41) being applied directly to the J input of each first flip-flop (263) and to the K input thereof by way of an inverter stage (264), the J of the second flip-flop (265) being connected to the Q1 output and the K inputs of both the first flip-flop (263) and the second flip-flop (265) being connected together.

25. A control device as claimed in claim 24, in which 45 the triggering inputs of the first and second JK flip-flops (263, 265) form the synchronizing input of the synchronizing gate (121), the gate (121) further comprising a first AND gate (266) having inputs connected respectively to the synchronizing input (121) and the Q1 output of the first JK flip-flop (263) and a second AND gate (267) having inputs connected respectively to the Q1 output of the second JK flip-flop (265) and to said synchronizing input (121).

26. A control device as claimed in claim 25, in which the output of the first AND gate (266) is connected to the transfer command input (H) of the final reading store (123) and the output of the second AND gate (267) is connected to the reset input of the forward counter (122).

27. A control device as claimed in claim 22, in which the forward counter (122) comprises

55 a plurality of interconnected JK flip-flops (256-259) whose triggering inputs are interconnected to form the counting input (z), the reset input (R) being common to the plurality of JK flip-flops (256-259).

28. A control device as claimed in claim 22, in which the final reading store (123) comprises a plurality of D flip-flops (260-262) whose triggering inputs are interconnected to form the transfer command input (H) and whose D inputs are connected to the binary number output of the forward counter (122).

29. A control device as claimed in claim 18, in which the computing circuit comprises a first multiplier (64) having two inputs to which the outputs of the two interpolators (58, 61) are connected, the output frequency of said multiplier being fed at least indirectly to said solenoid (32, 33) of the fuel injection valve (29, 30).

30. A control device as claimed in claim 29 for an engine having a throttle, or butterfly valve (23), which includes a decoder (FIG. 1: 48) responsive to the position of the throttle or butterfly valve (23) of the internal combustion engine (20) and in which the computing circuit comprises a second multiplier (65) having two inputs connected respectively to the output of the first multiplier (64) and to the decoder (48).

31. A control device as claimed in claim 30, wherein the decoder (48) comprises (FIG. 15) a logic network 25 having logic gates (271-274), and two switches (45, 46) the first (45) of which is operable when the throttle or butterfly valve is in the idling position, and the second (46) of which is operable when the throttle or butterfly valve is in its full load position, the logic gates being controlled by said switches.

32. A control device as claimed in claim 1 further comprising

a voltage/frequency converter (67) for producing a frequency which increases with increasing voltage of the power supply for the solenoid (32, 33), and in which said computing circuit comprises a frequency converter (68) whose input is connected to the output of the voltage/frequency converter (67) to provide a frequency which decreases with increasing power supply voltage, and an adder (69) having two inputs of which one is connected at least indirectly to the output of said at least one interpolator (58) and the other is connected to the output of the frequency converter (68), the output of the adder (69) being fed at least indirectly to said solenoid (32, 33).

33. A control device as claimed in claim 32, in which the frequency converter (68) comprises a divider to 50 which a strobing pulse train (f_{02}) is applied as a dividend and to which the output frequency (f_4) of the voltage/frequency converter (67) is applied as a divisor.

34. A control device as claimed in claim 33, wherein the divider comprises

(FIG. 6) a forward counter (127), a final reading store (128) whose inputs are connected to the binary number output of the forward counter (127), and a synchronizing gate (126), a first output of which is connected to a reset input (R) of the forward counter (127) and a second output of which is connected to a transfer command input (H) of the final reading store (128), the strobing pulse train (f_{02}) being applied to the counting input of the forward counter (127) and the output (f_4) of the voltage/frequency converter (67) being applied to the input of the last-mentioned synchronizing gate (126).

35. A control device as claimed in claim 34, in which the synchronizing gate (126) has a synchronizing input to which a strobing pulse train (f01) is applied.

36. A control device as claimed in claim 34, and further comprising at least one additional counter (122), final reading store (123) and gate (120);

wherein the forward counter (127), the final reading store (128) and the synchronizing gate (126) are of the same construction as the additional forward counter (122), the final reading store (123) and the synchronizing gate (120).

37. A control device as claimed in claim 34, wherein the frequency converter (68) comprises

(FIG. 6) a series multiplier comprising a divider-counter (106) and a divider-gate (129) connected to the outputs of the divider-counter (106), the divider-gate (129) being connected between the output of the final reading store (128) and said other input of the adder (69).

38. A control device as claimed in claim 1, in which the frequency/digital converter (57) comprises

(FIG. 5a) a forward/backward counter (101) and a feedback loop including a digital/frequency converter (102, 106) arranged between the binary number output (g1) and the counting input (z) of the forward/backward counter (101).

39. A control device as claimed in claim 38, in which the digital/frequency converter (102, 106) is a series multiplier and includes a central divider-counter (106) and a divider-gate (102) connected to the outputs of the central divider-counter (106).

40. A control device as claimed in claim 39, in which the central divider/counter (106) has a plurality of groups of outputs and one group being connected to said divider-gate being connected to effect division counting in other circuits of the device whereby said central divider/counter will be common to the device.

41. A control device as claimed in claim 40, in which the central divider/counter comprises the divider/counter (106) forms the divider counter of claims 10 and 37.

42. A control device as claimed in claim 39, comprising (FIG. 5a) subtractor (98) connected by its output to the counting input (z) of the forward/backward counter (101), the input signal (f1) to the frequency/digital converter (57) and the output frequency (f16) of the divider-gate (102) being applied to respective inputs of the subtractor (98).

43. A control device as claimed in claim 42, comprising a frequency divider (99) arranged between the output of the divider-gate (102) and the input to the subtractor (98).

44. A control device as claimed in claim 42, in which an oscillation suppressor (100) is arranged between the subtractor (98) and the counting input (z) of the forward/backward counter (101), the oscillation suppressor also controlling the counting direction input (d) of the forward/backward counter (101).

45. A control device as claimed in claim 44, in which the oscillation suppressor (100) comprises

(FIG. 9a) a D flip-flop (175) whose D input is connected to the input of the subtractor (98) which receives the pulses to be counted negatively and whose triggering input is connected to the output of the subtractor (98), an EXCLUSIVE OR gate (176) whose two inputs are connected to the D input and the Q2 output of the D flip-flop (175),

and a NAND gate (177) whose first input is connected to the triggering input of the D flip-flop (175) by way of an inverter (178) and whose second input is connected to the output of the EXCLUSIVE OR gate (176), the output of the NAND gate (177) being connected to the counting input (z) of the forward/backward counter (101) and the Q2 output of the D flip-flop (175) being connected to the counting direction input (d) of the forward/backward counter (101).

46. A control device as claimed in claim 42, comprising (FIG. 9a) respective first (97) and second (172) strobing stages connected to the inputs of the subtractor (98) to apply said input signal (f1) and said output frequency (f16), respectively therethrough to the subtractor (98).

47. A control device as claimed in claim 46, in which the first strobing stage comprises a series combination comprising first (167) and second (170) D flip-flops whose triggering inputs are controllable by a stepping pulse train (f01) inverted in an inverter stage (169), the input signal being applied as a frequency to the D input of said first D flip-flop (167), and a NAND gate (171) whose output forms the output of the first strobing stage (97) and whose two inputs are connected respectively to the Q1 output of said first D flip-flop (167) and the Q2 output (171) of said second D flip-flop.

48. A control device as claimed in claim 43, comprising

(FIG. 9a) a strobing stage (172) connected between the output of the frequency divider (99) and the subtractor (98), and including

a D flip-flop (172), whose triggering input is connected to an inverted stepping pulse train ($-f01$) and whose D input is connected to the output of the frequency divider (99), and a NAND gate (173) whose two inputs are connected respectively to the D input and the Q2 output of the D flip-flop (172) and whose output is connected to the subtractor (98).

49. A control device as claimed in claim 46, in which the subtractor (98) comprises an EXCLUSIVE OR gate (98) whose two inputs are connected to the outputs of said first and second strobing stages (97, 172).

50. A control device as claimed in claim 49, comprising a NAND gate (174) connected by its first input to the input of the EXCLUSIVE OR gate (98) forming the subtraction stage by its second input to an inverted stepping pulse train ($-f01$) and having its output connected to the forward/backward counter (101).

51. A control device as claimed in claim 46, in which the first and second strobing stages (FIG. 9c: 97, 172) are similar.

52. A control device as claimed in claim 46, wherein the subtractor (98) comprises

(FIG. 9c) two AND gates (291, 292) each connected by one input via a respective inverter stage (293, 294) to the output of a respective one of the first and second strobing stages (97, 172a, 172), and by another input to the other of the first and second strobing stages,

and an OR gate (298), connected by its inputs at least indirectly to the outputs of the two AND gates (291, 292).

53. A control device as claimed in claim 52, wherein the oscillation suppressor (100) comprises a JK flip-

flop (295) whose J, K inputs are connected to the outputs of the two AND gates (291, 292), and further first and second AND gates (296, 297), two inputs of said first of which (296) are connected respectively to the J input and the Q1 output of the JK flip-flop (295) and two inputs of said second of which (297) are connected respectively to the K input and the Q2 output of the JK flip-flop (295), the outputs of the first and second AND gates (296, 297) being connected to the inputs of the OR gate (298).

54. A control device as claimed in claim 53, in which the output of the OR gate (298) is connected to the counting input (z) of the forward/backward counter (101), and the output of one of the further first and second AND gates (296, 297) is connected to the counting direction input (d) of the forward/backward counter (101).

55. A control device as claimed in claim 42, in which the divider-gate (102) has two frequency outputs (f_{12} , f_{13}), an adder (103), the two frequency outputs (f_{12} , f_{13}) being connected to inputs of the adder (103) whose output is connected to the input of the subtractor (98).

56. A control device as claimed in claim 55, in which the adder (103) comprises a NAND gate.

57. A control device as claimed in claim 55, comprising an adder circuit (107) whose inputs are connected to outputs of said central divider-counter (106) for producing a constant offset or shift frequency (f_{15}) which is fed to an input of the subtractor (98).

58. A control device as claimed in claim 57, comprising an additional adder (105), having its output connected to the input of the frequency divider (99), its inputs connected to the outputs of the adders (103) and the adder circuit (107).

59. A control device as claimed in claim 58, comprising respective strobing stages (104, 108) connected to the input of the additional adder (105).

60. A control device as claimed in claim 59, in which the adder circuit (107) and the respective strobing stage (108) together comprise a NOR gate (107) which has an additional strobe input (197).

61. A control device as claimed in claim 17, in which the second frequency/digital converter (60) is of the same construction as the frequency/digital converter (57).

62. A control device as claimed in claim 1, in which the interpolator (58) comprises

(FIG. 5a) a range or interval decoder (110); 50 a forward/backward counter (101); the output (81) of the forward/backward counter being connected to the input of the range decoder (110); and a constant store (112) and a slope store (115) whose inputs are connected to the digital output of the range decoder (119),

the constant store (112) and the slope store (115) serving to store reference constants and slopes to simulate the operating characteristics of the engine and to modify the output signal of the interpolator in relation to the input signal to be interpolated over different ranges of the input signal as determined by the range decoder (110) whereby the output signal will be, at any level, a function of the input signal as modified by the transfer function of the interpolator at the respective signal level or range.

63. A control device as claimed in claim 62, in which the range decoder comprises (FIG. 12a) NAND gates (231-239) whose outputs provide the decoder binary output and whose inputs are connected at least indirectly to those outputs of the forward/backward counter (101) associated with the highest binary digits.

64. A control device as claimed in claim 63, comprising inverter stages (232, 235), some inputs of at least some of the NAND gates (231-239) being connected via the inverter stages to the respective counter (101) outputs.

65. A control device as claimed in claim 62, in which the constant store (112) and the slope store (115) are in the form of wired stores.

66. A control device as claimed in claim 62, in which the interpolator (57) further comprises a series multiplier connected to the constant store (112) for producing the reference constants of the interpolated function according to the decoded ranges.

67. A control device as claimed in claim 66, in which the series multiplier comprises a divider-counter (106) and a separate divider-gate (111), the constant store (112) having a binary number output connected to the binary number input of the divider-gate (111).

68. A control device as claimed in claim 62, in which the interpolator (57) further comprises a series multiplier connected to the output of the slope store (115) for producing portions of the interpolated function linearly dependently upon the input frequency in the individual decoded ranges.

69. A control device as claimed in claim 68, further comprising a strobing stage (114) connected to the input (z) to the series multiplier.

70. A control device as claimed in claim 69, wherein the strobing stage (114) comprises

(FIG. 9a) an AND gate (114) of which a first input is connected to said divider-gate frequency output (f_{13}) NOR gate (195), and a second input of the AND gate (114) being connected to the output of the NOR gate (195), which has two inputs to which respective strobing pulse trains (f_{01}, f_{02}) are applied.

71. A control device as claimed in claim 68, wherein the series multiplier of claim comprises

(FIG. 5a) a divider-counter (113), and a divider-gate (102), the counting input of the counter (113) being connected to the frequency output of the divider-gate (102); and a second divider-gate (114), the slope store (115) having a binary number output connected to the binary number input of the second divider-gate (114).

72. A control device as claimed in claim 71, in which the interpolator further comprises

(FIG. 5a) an adder (116) whose output forms the output of the interpolator (57), the frequency outputs of the second divider-gate (114) and the separate divider-gate (111) being applied to respective inputs of the adder (116).

73. A control device as claimed in claim 72, further comprising respective strobing stages (113a, 112a) connected between the inputs of the adder (116) and the outputs of the divider-gates (114, 111).

74. A control device as claimed in claim 73, the device comprises more than one interpolator, and at least two interpolators are similar.

75. A control device as claimed in claim 74, further comprising

an oxygen measuring sensor (36) located to be responsible to exhaust gas from the internal combustion engine (20);

and a voltage/frequency converter (37) whose input is connected to the oxygen measuring sensor (36)

and whose output is connected to the computing circuit.

76. A control device as claimed in claim 75, wherein (FIG. 8a) the oxygen measuring sensor (36) and the voltage/frequency converter (37) connected thereto are connected in a servo-loop, said loop also comprising a subtractor or comparator (160) to compare a desired reference value with an actual value of the air number of the fuel/air mixture fed to the internal combustion engine, the voltage/frequency converter (37) being connected to a first input of the subtractor (150); and means to connect said reference value connected to the second input of the subtractor (160).

77. A control device as claimed in claim 76, in which said reference value connecting means comprises a multiplier (161).

78. A control device as claimed in claim 77, in which the multiplier (161) comprises

(FIG. 8a) a series multiplier including a divider-counter (106) and a divider-gate (162) connected to the outputs of the divider-counter (106);

a dividing factor store (163), the divider-gate (162) being connected between the dividing factor store (163) and the second input of the subtractor (160).

79. A control device as claimed in claim 78, wherein a central divider-counter (106) is provided in the device, and the divider-counter (106) comprises said central divider-counter.

80. A control device as claimed in claim 76, in which the servo-loop comprises an integrating controller (157) connected to the output of the subtractor or comparator (160).

81. A control device as claimed in claim 80, further comprising an oscillation suppressor (158) is arranged between the subtractor (160) of said integrating controller (157).

82. A control device as claimed in claim 80, wherein said integrating controller comprises a forward/backward counter (157).

83. A control device as claimed in claim 82, wherein the computing circuit further comprises

(FIG. 8a) a further multiplier (156) which has two inputs of which a first is connected to the output of the integrating controller (157); second is connected to the output of the interpolator (58), the output of the last-mentioned further multiplier (156) controlling said solenoid (32, 33) of the fuel injection valve (29, 30).

84. A control device as claimed in claim 83, further comprising means (69) connecting a signal representative of supply voltage for the solenoid (32, 33) to the second input of the further multiplier (156).

85. A control device as claimed in claim 82, in which the computing circuit comprises

(FIG. 8b) an adder (165) whose inputs are connected to the output of said integrating controller

(157); and means (69) connecting a signal representative of operating parameters affecting the device to the input of said adder (165), the output of the adder (165) controlling the solenoid (32, 33) of the fuel injection valve (29, 30).

86. A control device as claimed in claim 85, wherein said connecting means comprises a signal adder (69) having engine operating parameter signals applied thereto, said signal adder (69) being connected to the second input of the adder (165).

87. A control device as claimed in claim 85, in which said servo-loop includes (FIG. 8b) a digital/frequency converter (106, 166) which arranged between the integrating controller (157) and the adder (165).

88. A control device as claimed in claim 83, further comprising a frequency/time converter (70), the output of the further multiplier (156) being connected to the input of said frequency/time converter (70).

89. A control device as claimed in claim 85, further comprising (FIG. 8b) a frequency/time converter (70) the output of the adder (165) being connected to the input of said frequency/time converter (70).

90. A control device as claimed in claim 82, further comprising a frequency/time converter (70) (FIG. 8c) having two inputs (f_7, f_9), said servo-loop comprises a digital/frequency converter (106, 166) connected between the forward/backward counter (157) and an input (f_9) of said frequency/time converter (70).

91. A control device as claimed in claim 90, wherein (FIG. 8c) the frequency/time converter comprises a backward counter (141) and the output of the digital/frequency converter (106, 166) is connected as a stepping input (f_9) to the backward counter (141).

92. A control device as claimed in claim 89, in which the digital/frequency converter (106, 166) comprises (FIG. 8b) a series multiplier comprising a divider-counter (106) and a divider-gate (166) connected to the outputs of the divider-counter (106), the divider-gate (166) being connected between the output of the forward/backward counter (157) and the frequency/time converter (70).

93. A control device as claimed in claim 92, wherein a central divider-counter (106) is provided in the device and the divider-counter (106) comprises said central divider-counter.

94. A control device as claimed in claim 1, wherein the device has at least one multiplier 64, and said multiplier comprises

(FIG. 4a) a series multiplier and comprises a divider-counter (71) and a divider-gate (72) connected to the divider-counter outputs.

95. A control device as claimed in claim 94, in which the divider-gate (72) comprises a decoding portion (87) for decoding the outputs of the divider-counter (71) and a pulse synthesis portion (88) to provide a pulse train from the decoded outputs.

96. A control device as claimed in claim 95, in which said synthesis portion (88) includes an output OR gate (95), and AND gates (92-94), equal in number to the number of stages of the divider-counter (71) connected to the inputs of the output OR gate (95).

97. A control device as claimed in claim 96, counting input (76) of the divider-counter (71) forms the first input of the respective multiplier, and the second input of the respective multiplier is in the form of a binary number input (84, 85, 86) whose individual binary digit

inputs are each connected to an input (84-86) of a respective one of the AND gates (92-94).

98. A control device as claimed in claim 96, in which said decoding portion (87) includes a plurality of logic gates (89-91) whose inputs (80-83) are connected to the outputs of the individual stages (73, 74, 75) of the respective divider-counter (71) and whose outputs are connected to respective inputs of the AND gates (92-94).

99. A control device as claimed in claim 1, further comprising

(FIG. 11a) a common pulse generator (109) for supplying strobing pulse trains (f_{01} - f_{04}) to strobing stages and means generating a clock pulse train (f_0) and controlling the common pulse generator (109).

100. A control device as claimed in claim 99, the common pulse train generator means comprises a crystal oscillator for producing said clock pulse train (f_0).

101. A control device as claimed in claim 99, wherein the device comprises synchronizing gates the flip-flops, and the strobing pulses for said gates and flip-flops are provided by said common pulse generator.

102. A control device as claimed in claim 1, wherein the device has a central divider-counter, which comprises

(FIG. 10) a forward counter (198) to which a stepping pulse train (f_{05}) is fed and a decoding portion (199); the device has divider-gates connected to the decoding portion of said central divider-counter.

103. A control device as claimed in claim 99, wherein the device has a divider-counter operating in accordance with clock pulses, in which said stepping pulse train is provided by said common pulse generator as the clock pulse train.

104. A control device as claimed in claim 102, in which each divider-gate (111) connected to said central divider-counter (106) comprises

(FIG. 13) a group of AND gates (241-248) equal in number to the number of stages of the forward counter (198), and at least one output OR gate (249) connected by its inputs to the outputs of the AND gates of the group (241-248).

105. A control device as claimed in claim 104, in which the decoding portion (199) includes a plurality of logic gates (200-218) whose inputs are connected to the outputs of the individual stages of the forward counter (198) and whose outputs are connected to respective inputs of the AND gates of the group (241-248).

106. A control device as claimed in claim 1, wherein the device includes at least one voltage/frequency converter (39) which comprises (FIG. 16a) a voltage-controlled oscillator.

107. A control device as claimed in claim 106, in which said voltage-controlled oscillator comprises

(FIG. 16a) a first operational amplifier (275) whose output is connected to its inverting input by an integrating capacitor (281), the input voltage (277) to be converted into a frequency being impressed upon one input (inverting) of the first operational amplifier whilst a reference voltage (289, 290; 279, 280) is applied to its other input;

a second operational amplifier (283) connected by one input (inverting) to the output of the first oper-

ational amplifier (275) and by its other input to a reference voltage; and a semi-conductor switch (282) in parallel with said integrating capacitor (281), the output frequency of said voltage/frequency converter appearing at the output of the second operational amplifier (283), said second operational amplifier being connected to control said semi-conductor switch (282).

108. A control device as claimed in claim 1, in which the oscillator is in the form of an LC oscillator having a coil element (27) and a core element (26) movably arranged in the coil element;

a baffle plate (25) is arranged in the flow of intake air to the engine (20); and one of the elements is secured to the baffle plate to move therewith.

109. In combination with an internal combustion engine having an air induction pipe, a central device for controlling at least one solenoid operated (32, 33) fuel injection means (29, 30) in dependence upon the rate of air flow, comprising

an air flow sensing transducer means (25, 26, 28, 57) to be arranged in the induction pipe of the engine and including

means responsive to air flow and providing a corresponding signal, an oscillator having its frequency of oscillation controlled by air flow through the air flow responsive means so that the output frequency of the oscillator will be dependent upon and a function of the rate of the air flow, and a frequency/digital converter connected to said oscillator and providing a digital air flow output signal in digital form as a function of the frequency of the oscillator;

and a digital computing circuit having an input connected to be responsive to said air flow digital signals and having an output for controlling the fuel injection means (29, 30, 32, 33), said computing circuit comprising

a digital differential analyzer whose input is responsive to signals in digital form, and at least one interpolator (58, 61) storing simulated engine operation characteristics to modify the signal from said air flow transducer means in accordance with the operating characteristics of the internal combustion engine.

110. In combination with an internal combustion engine, a control system, in which the engine (20) has an air induction pipe, at least one fuel injection valve (29, 30), a solenoid (32, 33) controlling the operation of the injection valve, said system comprising

transducer means responsive to a respective engine operation, or operating parameter and providing a parameter output signal in digital form, said transducer means including means sensing an engine operation or operating parameter and having a corresponding variable output;

a variable frequency oscillator having a frequency variation control element, said control element being operatively connected to said sensing means to vary the frequency of the oscillator in accordance with said variable output;

and frequency/digital conversion means converting said variable frequency into a digital signal to provide a digital parameter output signal;

a computer network having a digital differential analyzer;
function storage means storing at least one transfer function of the engine fuel supply with respect to an operation, or operating parameter of the engine to simulate the operation and behavior of the engine upon variation of the respective parameter, the parameter output signal from said transducer means being connected to the computer network input to be processed therein and to develop a derived output signal, in digital form, as modified by said transfer function in the function storage means and simulating engine operation or behavior, with respect to the instantaneous value of said parameter signal;

and digital-time conversion means connected to the solenoid of the injection valve having said computed output applied thereto and converting said output into a signal of such time duration that the injection valve is energized to open as determined to be appropriate to the engine with regard to the instantaneous engine operation, or operating state as sensed by said transducer means.

111. System according to claim 110, wherein a power supply is provided and wherein at least two transducer means are provided, each responsive to at least one parameter, said parameters comprising:

air flow through the engine induction tube;
engine temperature;
engine exhaust gas composition;
engine speed;
power supply voltage;
engine throttle position;
each said transducer means providing a respective parameter output signal in digital form, as a function of frequency of the respective oscillator, to said computer network;
a plurality of transfer function storage means, one for each of said at least two parameters, the respective digital parameter signal being applied to the respective transfer function storage means to develop respective developed output signals;
and wherein said computer network further comprises combining circuit means logically combining

the derived output signals and developing a composite, derived output signal, in digital form, said composite derived output signal being applied to said digital-time conversion means, whereby the energization time of the injection valve, or valves will be a function of at least two of said parameters.

112. System according to claim 111, wherein some of the transducer means comprises

at least one other of the transducer means comprises means sensing an electrical output voltage representative of a respective parameter;
a voltage controlled oscillator having a variable frequency output, the frequency variation depending on and being a function of the variable voltage;
and frequency/digital conversion means converting said variable frequency, as controlled by said variable voltage, into a digital signal to provide one of said digital parameter output signals,

113. System according to claim 111, wherein said transducer means comprises means sensing the respective engine operation or operating parameter and providing an electrical output quantity, the level of which is representative of said respective parameter;

a variable frequency, electrically controlled, oscillator having its oscillation frequency controlled by said electrical quantity to provide an output signal, the frequency of which varies in accordance with said level, and hence said variable parameter;
and frequency/digital conversion means converting said variable frequency into a respective digital signal to provide a respective one of said digital parameter output signals.

114. System according to claim 110, wherein said valve is a two-position valve of the ON-OFF, or OPEN-CLOSED type;

and said output signal has a time duration which controls the open time of the valve.

115. System according to claim 110, wherein said valve is of the continuously open type;
and said output signal has an average energy which controls the extent of opening of the valve in accordance with said average energy.
